2,055,463

COMBINATION OF TYPOGRAPHIC MACHINES

Alexander Block, New York, N. Y.

Application June 28, 1929, Serial No. 374,554

47 Claims. (Cl. 199—11)

This invention relates to machines adapted for the printer's art, embracing such units as typesetting, typewriting, typeprinting, matrix-setting and casting machine devices, and more particularly, a photo-printing machine arranged to photograph and print on sensitized metal sheets or plates, lines of characters or single characters at a time, or otherwise, and upon the completion of a set number of lines, characters, or a full page, to automatically develop the photographed matter in a developing chamber attached thereto, and containing the suitable developing solution.

The complete machine as shown on Sheet 1 of the annexed drawings is intended as a compact printer's outfit, comprising machine elements which can serve every need of the commercial printer, the book and magazine publisher and may also be adapted for modern newspaper publication, as a revolutionary improvement upon the cumbersome and expensive outfits now in use. Although this comparatively small and compact typesetting, typewriting, casting and photoprinting, as well as printing units, include in their printing family the typesetting and line casting outfit at present in common use, particular attention is called to the photoprinting machine and its adaptation for preferably photoprinting lines of printed matter at a time, as above mentioned, until a complete page or column of matter had been transferred to the sensitized plate.

It is in this latter machine that lies the greater novelty and utility, it is believed, and its applicability for all purposes known to the printing art. With means provided for magnifying or reducing characters, lines, phrases, and so on to any desired size, upon delivery of the printed or type-written matter to the camera focus for photoprinting, necessitating the employment of but one font of type of uniform size, from the smallest, such as six point to the larger sizes, such as eighteen to twenty-four and so on, for the achievement of that purpose.

It is conceivable that each of the machine units incorporated in the printer's and publisher's armamentarium disclosed in the appended drawings, may serve as a separate machine unit, apart from the other machine elements embodied in the whole outfit. And it must be apparent to any party acquainted with the art appertaining to this type of machines that each of said machines, as a unit element, is a radical departure from any of their analogous apparatus now in common use in the industry. However, the mechanical connection for their individual and combined operation is such as to warrant the filing

of the whole combination of machine units under one application for Letters Patent, instead of under separate and distinct applications required by the rules of practice where the mechanical connection is not as distinct as in the present instance. Wherefore, the present applicant takes the liberty of embodying all of the devices, of novel and useful construction—each and every one of them, under the one present application.

It must be further apparent that the construction of the machine, as a whole, or as to each individual unit, or any part thereof, may be altered in a slight way, as to form, size, or arrangement of parts, without in any way interfering with the spirit of the invention, the essential elements of their novelty and utility being preserved throughout. The construction and arrangement of parts as disclosed in the annexed drawings being submitted herewith for purposes of demonstration only of the points desired to be covered by Letters Patent, like characters representing like parts throughout in the said appended drawings, wherein—

Figure 1 shows a top plan view of the combined machines, embracing the type-setting unit A, the line writing or printing unit B, the photoprinting machine C, the printing drum press D, and casting unit E.

Figure 2 shows a longitudinal vertical section of the machine unit A of Figure 1, demonstrating its novel manner of delivery of types or matrices to a common point and the steady replenishment of newly-stamped type or matrix units by novel means connected with the supply font.

Figure 3 is a sectional view of another type of machine, adapted for both writing or printing characters as in a typewriting machine as well as simultaneously delivering individual type to a typeholder, where desired, for certain types of work. This machine making it possible to write the subject matter on a sheet of paper and to simultaneously set the type for multigraphing and/or printing the said subject matter in desired quantity, either with the ragged edge of the typewritten letter, or with the justified line, as in regular printed work.

Figure 4 shows a modified type holder, arranged for holding and delivering capitals and small character type, disclosed in the patent for Typesetting machine granted to the present applicant on March 30, 1920, Number 1,335,217, the application for which was filed October 4th, 1917.

Figure 5 shows the type or matrix receiving and feeding device, for delivering same into the holder. Figure 6 is a top view thereof as it is seen

when at rest with its type-holding slot directly over the type-receiving channel. Figure 7 is an open-end view thereof. Figure 8 is a longitudinal vertical section of same.

5 Figure 9 shows the stamping element in one operative position.

Figure 9a shows the stamping element in another operative position.

10 Figure 9b shows the stamping element in a third operative position.

Figure 10 shows the actuating element of the stamping mechanism.

Figure 10a shows the actuating element of the corresponding stamping mechanism.

15 Figure 11 is another view of the type-receiving and feeding device, disclosed in Figures 5, 6, 7 and 8. Figure 12 shows the type-channel to which the type or matrices are fed by the device above-mentioned, with parts broken away.

20 Figure 13 is a front plan view of the casting mold, for preferably casting lines of type, as hereinafter set forth, with parts broken away.

Figure 14 is a front perspective view thereof showing the ejecting means, with parts broken away.

25 Figure 15 is a side edge view thereof. Figure 16 shows a cross-section of the type or matrix channel. Figure 17 gives a rear view of the said mold. Figure 18 is a cross section thereof along line A—B. Figure 19 is a side view of 30 same, showing one of the slug ejectors. Figure 20 is an edge view of an ejector. broken away. Figure 37 is a longitudinal vertical section of the said printing apparatus, with some of its actuating means, parts broken away. Figure 38 is a side plan view of same, with parts missing and parts broken away. Figure 39 is another side view of same, in connection with operating apparatus. Figure 40 shows the mechanism for adjusting the focal distance of camera with relation to the delivered written or printed matter, for photographing purposes in varying type sizes, parts broken away, other parts missing. Figure 41 is another arrangement of same, with more parts missing and others broken away. Figure 42 is the device for unlocking the operated keys of keyboard KF when desired.

10 Figure 43 is a vertical longitudinal section through line C—D of phototyping apparatus C and its developing chamber, with many parts omitted, other parts broken away. Figure 44 shows the means for operating the disclosed shutter structure of the camera, parts missing and others broken away. Figure 44a is a detail of Figure 44.

15 Figure 45 shows a front view of the mechanism for ejecting the set of type or printed line, either 20 into the mold channel, or printing apparatus. Figure 46 shows an upper view of the handle and the ejecting prongs of the said ejecting mechanism, or rather shifting mechanism, with parts broken away. Figure 47 is an end view of said 25 shifting mechanism.

Figure 48 is a view of the inner face of the front of the phototyping chamber with its line 30 of printed matter delivered into focal position for phototyping purposes. Figure 49 shows two photoprinted words, with the beginning character W magnified to emphatic size by comparison with the rest of the printed characters.

35 Figure 50 shows the sensitized metal, paper or otherwise prepared photographic film and the mechanism for linespacing same and delivering it into the developing chamber. Figure 51 is a view of another type of camera shutter and its manner of operation. Figure 52 is a front face view of said camera shutter. Figure 53 is a side 40 view of the phototyping-developing chamber, with the linespacing and developing mechanism shown in part on the outside of the machine, the chamber in part broken away. Figure 54 is a transverse sectional view of another means of 45 feeding the paper or metal film for phototyping a word or line at a time, or separate characters where desired.

50 Figure 55 is an upper view of a combined type-printing or writing machine with a phototyping apparatus incorporated therewith, and direct means provided for delivering the printed line from the typewriting or printing machine to the focal position of the phototyping chamber, for phototyping the said line onto preferably sensitized metal sheets or plates, and for then returning the holder channel to its typewriting position.

55 Figure 56 discloses a printing unit of the type-printing machine and the novel feed mechanism connected therewith. Figure 57 shows the feed mechanism, parts broken away. Figure 58 is a view of the cutting off knife. Figure 59 is a sectional view of the knife on line A—B. Figure 60 is a rear edge view of said knife, part broken 60 away. Figure 61 is an actuating device for delivering word spacing devices to the printing channel for justifying automatically. Shown in side and edge view. Figure 62 is a side view of actuating device holding a spacing device, the 65

said actuating device shown pivotally mounted and connected with its operating means.

Figure 63 shows the mainspring connected to a shifting mechanism for feeding severally spacing devices to the above-mentioned individual actuating device. Figure 64 is a cross section thereof showing the two members, one stationary, the other movable on roller bearings along a track. Figure 65 is a transverse section of the two elements, with the ball bearing, shown apart.

Figure 66 shows the free end view of the spring-pressed device of the traveling type holder. Figure 67 is a perspective of an end part of said traveling type holder. Figure 68 is an end view of said type holder. Figure 69 is an adjustable stop for said traveling type holder, adjustable for various size lines. Figure 70 is a perspective front view of the said traveling type holder. Figure 71 is a perspective view of the said spring-pressed device. Figure 72 is a cross section thereof. Figure 73 is an end view of another type of traveling type holder. Figure 74 is a top view of said spring-pressed device of the traveling type holder. Figure 75 is an upper view of the cutting off knife and its shifting device connected therewith.

Figure 76 shows the mechanism connected with lever 241 disclosed in Figure 55, for operating all of the other mechanisms of the machine beyond the typeprinting or typewriting, through the photoprinting stage and return.

Figure 77 the justifying actuator and the device for shifting back the spacers into the space holder against the resistance of the above-mentioned mainspring. Figure 78 shows the justifying actuator in connection with its operating means. Figure 79 shows a type holder returning to typeprinting position and the means for ejection of the photographed line of printed matter, parts broken away. Figure 80 is a view of the means for operating the device for shifting the spacers. Figure 81 constitutes the means for successively actuating the knife and the space actuator from said main lever 241 preparatory to justifying of the line and moving the traveling typed-line holder into photoprinting position. Figure 82 are rear edge views of knife and space actuators and their actuators as shown together. Figure 83 shows the same shown separately. Figure 84 discloses side views of said knife and spacing actuator and the means connected with space bar 2s for performing the cutting off function and delivering of a spacer into the traveling typeprint holder.

Figure 85 is a side view of said machine disclosed in Figure 55, with parts missing and other parts broken away. Figure 86 shows the end view of the foot lever 305 connected with the developing chamber of the said machine. Figure 87 shows a spring-pressed device for locking the said foot lever, to prevent its return to its complete resting point. Figure 88 shows a sectional view of the inside of the developing chamber, broken apart, with cam grooves on the wall for moving the developing table back and forth in an oscillatory movement, sideways and up and down. Figure 89 shows the line space wheel and its actuating lever for linespacing the film, and a device connected therewith for adjusting for variable spacing and for disconnecting the line space mechanism.

Figure 90 shows the means in loose operative connection with universal bar 194 and operated from the keyboard for individual character spac-

ing for different thickness of different printer's type, such as indicated in the figure.

Figure 91 shows one means of justifying a line of printed or typewritten matter, other than by the aforescribed spacing devices.

Figure 92 shows part of the mechanism for operating the shutter of the camera, such as completely shown in Figure 85.

Figure 93 shows the rack in operative connection with main lever 241, for operating the structures disclosed, as hereinafter set forth.

Figure 94 shows an index plate and the index lever for justifying the lines by mechanism disclosed in Figure 91.

Figure 95 shows the feed mechanism, with one feed roll in view, a thumb wheel, the toothed feed wheel and its retention spring, part broken away, and the spindle broken across.

Figure 96 shows a variable word spacing device controlled from keys, such as arranged at the front of the machine disclosed in Figure 55, the means of adjustment as hereinafter set forth, and side views of three of the variable justifiers and their relationship to the universal bar 194, all as controlled from keys 335.

Figure 97 shows a line of printed matter requiring no justification, the entire line being filled out. Figure 98 shows a line of printed matter requiring justification, and in this instance to be properly justified by means as hereinafter set forth from keys 335. Figure 99 is a justifying scale, arranged to be employed as hereinafter set forth.

Figure 100 shows the mechanism for pasting backs onto the printed words justified and held in position by the aforementioned spring-pressed lever, wherever desired to keep the original printed lines. An upper view of the rest of the pasting mechanism appears in Figure 55. Figure 101 shows a side view of the knife forming an integral part of said pasting mechanism for cutting off the paster at proper length and for shifting it a distance into the traveling type holder. Figure 102 is a cut away free end of one of the pasting mechanisms, showing the paster guide and slot for receiving shifting member of the knife. Figure 103 is an upper edge view of the knife. Figure 104 is the mechanism for actuating the pasting compressors. Figure 105 is the guide compressor to which the paster is fed.

Figure 106 is a device for increasing and/or diminishing the focal distance between the camera lens and the matter delivered for photoprinting, as hereinafter set forth. Figure 107 shows two characters on a type head, appearing in white on black for use in individual character photoprinting employed in connection with machine disclosed in Figure 112. Figure 108 shows an index plate and lever indicator for setting and maintaining the lens wheel disclosed in Figure 106, for increasing or diminishing the size of the printed letter or word or line delivered into focus for photoprinting, as set forth in the specification. Figure 109 is a view in reverse of the structures shown in Figure 79, where the traveling type holder travels in the reverse direction. Figure 110 shows a circle of small holes in the index device for receiving an indicator lever pin for locking the lens wheel in a desired position. Figure 111 is a side view of said indicator lever, with parts broken away and showing the pin arranged to be inserted into the holes disclosed in Figure 110.

Figure 112 shows a longitudinal vertical section

of the individual character phototyping machine and its developing chamber.

Figure 113 shows novel mechanism controlled from a keyboard, for stamping letters into metal or other suitable material, preferably by motor-driven mechanism, such as hereinafter set forth. Figure 114 shows the motor-driven mechanisms for performing the stamping operations, upon delivery of the punch and die members into the stamping position. Figure 115 shows the mechanism for feeding the strip to be stamped. Figure 116 shows the cam groove or slot for guiding the movement of the actuating lever arranged to operate the stamping mechanism. Figure 117 shows an edge view of the forked actuating lever.

Figure 118 shows the broken off cam end of the carrier in loose operative connection with switch 89c. Figure 119 shows the switch and its detent means.

Figure 120 is a side view of the automatic stamping mechanism. Figure 121 shows the tape feed mechanism mounted upon a frame adapted for shifting for capitals. Figure 122 is an edge view thereof showing the connection with the shift key.

Figure 123 shows a side view of the phototyping machine, with parts missing and other parts broken away, adapted for automatically phototyping a page of printed or written matter, line by line, until the completion of the page.

Figure 124 is a diagrammatic plan view of the automatic power-driven mechanism for successively and consecutively operating the various mechanisms of the machine units, with which they are in operative connection. Figure 125 shows the one-way trip actuator in operative connection therewith.

Figure 126 shows a switch for controlling the receiving end of the mold channel and the drum channel. Figure 127 is another view of same.

Figure 128 shows essential structures of my automatic type-writing and/or phototyping machine. Figure 129 is a front plan view thereof and its operative connection with motor-driven means, for automatically operating the machine. Figure 130 shows the segmental support for the type or letter bars of said automatic machine.

Figure 131 is a side view of the typewriting-printing-typesetting machine showing a combination hand-foot lever for operating the line casting mechanism, comprising the melting pot, the filling of the mold with metal and delivering the molds to their corresponding positions for performing their varied functions, as herein-after set forth. Figure 132 is an end view of its forked one-way trip actuator.

Figure 133 shows a side view of the automatic typewriting and/or phototyping machine, with parts missing and other parts broken away.

Figure 134 shows an upper plan view of my machine arranged for type-setting, type-stamping, typewriting or printing, line casting and phototyping, all combined in compact form, containing the essential elements of a complete typographic outfit, in its makeup. Figure 135 is a view of the mold carriage and its means for ejecting. Figure 136 is a sectional view of a part of a mold. Figure 137 is a cam plate for coacting with the mold for ejecting the matrices. Figure 138 is the rocker bar means for operating the melting pot. Figure 139 is a broken off end of lever 489 and its operative connection.

The brief description of the figures in the accompanying drawings should make it apparent

that the connection between the various machine units disclosed as a combined typographic armamentarium in Figure 1 and elsewhere in the said drawings is such as to warrant the incorporation of all those apparently separate units in the one present application for Letters Patent. Because of their structural and functional interdependence, the said units are or may be inseparably connected in structure and operative relationship with reference to one another, and may, therefore, for practical purposes be regarded as a composite working unit.

Concrete evidence thereof is to be found in the structural connection between the different units, as manually controlled by shift levers 241 shown in Figures 55 and 85,—89, 89e and 89t shown in Figure 1 and elsewhere throughout the drawings. More particularly is that true of lever 241, corresponding to the line space lever of the typewriting machine. This lever controls and is arranged to operate structures of several machine units connected with one another, by a single sweep in its operative direction, successively operating structures of the typeprinting machine and the phototyping machine and so on, to the completion of their several functions.

It is conceivable how a lever such as the one designated 241 in Figures 55 and 85 does and or may link in structure and operation a number of apparently separate machine units such as disclosed in the appended drawings: namely, a typewriting, typeprinting and/or typesetting machine unit, with a phototyping, justified-line-printing, regular printing and line slug casting machines. As disclosed in the annexed drawings, it must be reiterated that the apparently separate machine units are or may be linked structurally and functionally and are or may be interdependent and inseparable as working units for the achievement of a co-operative result—printing, either by means of linotype slugs of Mergenthaler identity, or through the more novel, modern and efficacious method—the line phototyping method, or single-character-at-a-time phototyping, and so on.

The aforementioned switches 89, 89e and 89t further go to establish the intimate structural and functional relationship between the said machine units—A, B, C, D and E, which are thereby essentially interdependent in point of structure and operation and may therefore be appropriately presented in the herein application in compliance, rather than defiance of the rules of practice or the laws regulating patents in the United States Patent Office.

Having covered the brief description of figures in the annexed drawings and advanced valid reasons for the incorporation of the several machine units therein disclosed in the present application, let us proceed with the detailed description of my invention:

Machine unit A as shown in Figure 1, and its analogous devices, as disclosed in Figures 55 and 85 and Figures 112 and 114, and so on.

Machine unit A, as disclosed in Figures 1 and 2 is essentially a typesetting and/or matrixsetting machine, set type or matrices being adapted to perform printing or casting operations respectively, coacting with other and further structures in their corresponding units to which they had been delivered, for the achievement of their respective functions. Where cast linotype are required, the line of matrices set by machine unit A is delivered into the mold of casting unit E and the casting is automatically performed as

will hereinafter appear. Where printing or type-writing is required, a line of set type is or may be shifted into unit B for the performance of the printing operation. Where it is moreover further desired to photoprint the set material upon a paper film or sensitized metal sheet or plate, the printed matter is or may be shifted into the focus channel of the photoprinting machine unit C and that operation is or may be quickly and efficiently performed. Then, as a further and final step in the interdependent and consecutive operation of the varied machine units, the photoprinted work is or may be developed automatically in a developing chamber connected with the photoprinting machine, as shown in Figure 43, and designated TK, 301 of Figure 85 and 371 of Figure 112.

Typesetting machine unit A is also further adapted for multigraphing purposes, being connected by means of a direct delivery channel 9b, into which its own type-holding channel does or may empty, so that the line of set matter may be shifted onto segmental drum D embodied as one of the machine units disclosed in Figure 1. A switch 9s¹ does or may control the shifting of the line of set type to said drum D, being either locked against admission of the said type to channel 9b, where the aforementioned casting mold is or may be in operation, or open and forming a part of the channel 9b wall, where the multigraphing machine is or may be receiving type set by the typesetting machine unit.

As hereinabove stated, machine unit A is essentially a type-setting machine, structurally and functionally, comprising a keyboard 2 of standard typewriter arrangement, a series of type-holding or matrix-holding bars 4, feed channel 5 in connection with said bars, one swing bar 4 shown in its operative position, and further embracing a line shifting device 6, for shifting the set type or matrix line in the desired direction.

The standard keyboard 2 is provided with all the appurtenances of the typewriter keyboard, comprising shift keys and shift locking devices, as well as the customary space bar at the front of the machine, which in the present typesetting machine performs the spacing of words by setting uniform space lugs between words where ragged edge work of common typewriting is desired, or slugs of variable size are interposed between words where justified lines are desired, as in regular printing. To the rear of the machine are shown structures designated respectively 3 and 7, as constituting mechanism for stamping characters into metal or other kinds of slugs fed to the stamping units 3—7 from channels of magazines 40. The said stamping attachment comprises a series of punches and dies, severally designated as above stated, 3 and 7, respectively, arranged to stamp new characters, for delivery to corresponding feed channels 5, to be successively fed to type-holding end 4c of type-carrier 4, for replenishing the supply of type or matrices used up in the process of setting operations.

In Figure 1, my invention discloses in machine unit A, a pivotally mounted type holder 4, an individual unit of which is shown in Figure 4. My machine disclosed in Figure 2 preferably employs the plunger type-holder bar, 4, as corresponding to the plunger type bar of a particular class of typewriting machines, and it is thought, that for the present purposes herein fully described, the latter type of carrier 4 is to be preferred, for obvious reasons unnecessary to state herein.

As fully disclosed in Figure 2, a slug magazine

40 is arranged to supply preferably individual slugs for stamping individual new characters for feeding by means of gravity and mechanical devices, new types or matrices to the type-carrier 4, in operative connection with key lever 3a, controlled manually by key 2, the said key lever being pivotally mounted at 4a and moving against the resistance of spring 5a, tending to maintain it in its normal rest position. A link 45 pivoted at one end to type carrier 4 and at the other end to bell lever 44, the other arm of which is or may be connected by means of link 46 with the said key lever 3a.

Type carrier 4 is moved along guide 47 to and from its operative position, its typeholding end 15 being arranged to be delivered to a common point in a feed mechanism designated 48, which is adapted to receive the type or matrix contained in compartment 4c of type carrier 4, function as a guide for the holder head of carrier 4, and to 20 subsequently feed the said type or matrix to channel 9—10, respectively, depending upon the purpose to which the line of set material is to be put. Said feed mechanism 48 is or may be rotatably mounted upon machine frame 1, at 47, 25 and embraces in its compartments 43a—43b the common point of delivery, the said feed mechanism 48 comprises a pivoted portion mounted at 47 and a rectangular receiving part, designated 43, divided into an upper rectangular compartment 43a arranged to receive the holding head 4c of carrier 4, and a lower, narrower compartment 43b, into which the type or matrix is arranged to descend by gravity. Mechanism 48 being mounted upon a guide extension 49 of said 30 guide 47, and is provided with an extension 50, provided with a toothed member 51, arranged to mesh with mechanism controlled from a keyboard for variably rotating said mechanism 48, for bringing its compartment 43 into alignment with 35 the carriers as they are being successively delivered into setting position. The said rotating mechanism comprising a rack 51 connected by means of a link 51b with the bell lever 51c pivotally mounted at 51d and pivoted to a universal 40 bar through limb 51a.

The normal rest position of feed mechanism 48 is or may be as shown in Figure 6, with its rectangular guide 43 in alignment either with channel 9 or 10, depending upon the direction of 50 travel of the set line of type, the individual type or matrix being arranged to descend by gravity from compartment 43b to receiving channel behind plate 9a, to be subsequently shifted into the channel proper: 9 or 10.

The line of type or matrices, set in the above-described manner, may be shifted in the mold or drum direction, or in the opposite direction, to the printing unit B and photoprinting unit C, by manual or automatic means. The manual constituting a slide 6, provided with a handle 6a, feet 155, an ejector 156 carried upon a stem 157, all slidably mounted in machine frame 1, suitable grooves being provided for that purpose. The automatic mechanism for automatically operating the said shifting mechanism 6, preferably comprising chain and sprocket means, respectively designated 152 and 150, connected with power-driven means in operative connection with the various machine units. In the automatic means, the line shifting being controlled by switches 89 or 89e, depending upon the direction of delivery desired.

The line shifting of type or matrices to the printing drum D or mold M is or may be con-

trolled by switch 9¹, comprising a pivotal member 9² and a stop 9³, for closing opening 9³, when it is arranged for the mold M to receive a line of matrices, or for shutting off the mold 5 channel when a line of type is to be fed to channel 9^b, for delivery to a segmental printing drum D.

The above mentioned stamping mechanism 3—7, preferably embrace individual punches 3 and a solid die 7, fixed to the machine frame 1, and provided with depressed characters or females for the raised male characters of the corresponding punches 3. The stamping devices are 10 or may be preferably operated automatically by 15 motor driven means or other provided power, each punch 3 being connected by means of a link 3g to a power-operated crank device C¹, preferably constructed like an automobile crank, with its cross pieces C² fixedly attached a variable distance away from member C¹, an arrangement 20 intended to make it possible to perform stamping operations of one or several stamping units at a time with every revolution of the said power-driven crank C². Also, the initial position of 25 members C¹ with reference to said links 3g, serving as determining factors in the priority of operation of the corresponding punches and the consequent stamping of their corresponding characters; link 3g being pivotally attached by one 30 end to punch 3 at 3f and by its other end to cross piece C² of crank C¹.

Proceeding with the detailed description of my invention, Figure 3 discloses a modified form 35 which combines the typewriting typesetting mechanism in the one machine, for performing typewriting and/or typesetting operations simultaneously or interchangeably, at will, as controlled from the same keyboard, and performed by the same carrier 4, therein disclosed, carrying a type-head with type 4t thereon, and comprising a holder 4c for type or matrix slugs. The latter being replenishable preferably by the same means from a source of supply hereinabove described in connection with the description of Figures 1 and 2. 40 Carrier 4 is or may be adapted to deliver severally and successively, one type at a time, to channel 55a, and if desired to simultaneously typewrite the corresponding character onto a piece of paper upon a platen roll P, mounted upon the usual type 45 of traveling carriage employed in connection with standard typewriting machines. Channel 55a is or may be provided with means 55c carrying a cross head 55 adapted to act as a cover for channel 55a, to prevent the feeding of type or matrices thereto during operation of the several type bars 50 where typewriting alone is desired. Device 55c is or may be controlled from a keyboard, a link 57 connecting it with a key or lever arranged to move said device into and out of locking position 55 with reference to said channel 55a.

In Figure 55 is disclosed the preferred and what I regard as the most commonly efficient type of machine embodying my invention, complete in every essential detail, being provided with means 60 65 182 for justifying lines of set and/or printed matter; with traveling members 235 comprising channels 10 for holding lines of set or printed matter, arranged to be delivered into the focus 30 of a photoprinting machine C, where it is or may be 70 75 photographed, or, where matrices form the line of set matter, the carrier does or may deliver said line to a mould M for casting a line of type in solid slugs.

The machine embodying my invention disclosed 75 in Figures 55 and 85 is virtually a typewriting

machine of novel construction, being provided with a standard keyboard KB, provided with a space bar 2a for regular usual spacing between words and an auxiliary space bar 2s adapted for cutting the printed tape at the end of every printed 5 word, or where the words are too short, at the end of a suitable-sized phrase and for delivering a spacing device 182 into the channel 10 of traveling carrier 235, after each word or cut off piece, preceding the last word of the line, for the purpose of justifying the line, as hereinafter fully set forth.

The justifying mechanism disclosed at the back of the machine in Figure 55 comprises a series of spacing units 182 slidably mounted upon a traveling member 182ec provided with a raised stop 182ac, arranged to move along a track 210 on a fixed member 206, by means of a main spring 208 connected to said traveling member 182ec at 182bc, along a support 205, for said spacing units 20 182. Said support 205 comprising a groove 209 for housing of the said spacing units 182. The latter comprise a head portion 182a adapted for slidable movement in the said groove 209, a wider portion 182b, a unit spacing end 182 and a spring 182c 25 attached thereto and arranged, in conjunction with other spacing units inserted in the line of printed or set matter, to co-operate with their fellow spacing units in the justification of the line, upon operation of the justifying actuator Cc. 30 An individual spacing unit carrier 184 being provided, whereto carrier 182ec is arranged to feed a spacing unit at a time, by means of the spring tension of main spring 208, after it had delivered its cargo into the channel 10 of traveling carrier 35 235 and returned to its normal resting position. Said carrier or spacing unit actuator 184 comprising a groove corresponding to and in alignment with groove 209, wherein is received the head 182a of spacing device 182 with its attached 40 spring 182c. Said spacing device being mounted pivotally at 184ax as shown in Figure 62, connected by link 184t with revolving plate 200, revolved by means of a rack 201 and pinion 202 combination, all as illustrated in said Figure 62. 45 Or, as disclosed in the preferred way demonstrated in Figure 84, wherein knife 186 and spacing unit carrier 182 are successively operated for the performance of their respective functions, the one for cutting off the tape at the required point and 50 the other for inserting a spacing unit 182 into the channel 10 after the cut-off piece of tape 183. Their successive operation is or may be controlled from the aforementioned spacing bar 2s, connected by means of a link 186x with a toothed 55 rack 290, traveling at one end in a guide groove 186g and maintained by a spring 290s in operative position with reference to pinions 292 and 293, respectively attached to and arranged to operate their corresponding knife and spacing unit carrier. The said rack 290 being provided with two sets of teeth and blank spaces, as shown, arranged in such a manner as to make it possible to operate first the knife and then the said spacing unit actuator, without interfering with their relative 60 65 operations.

Spacing unit actuator 184, with its contained spacing unit 182 is or may be moved in the direction of channel 10 of traveling holder 235, with its spacing end inserted through slot 10a therein, 70 and its further movement arrested when it reaches a position with its head member 182 in alignment with groove 206 of justifying actuator Cc, when main spring 208 moves traveling member 182ec and the series of spacing units 182 carried thereon 75

a distance sufficient to eject the spacing unit contained in actuator 184 and move it into groove 206 of mechanism Cc, feeding another spacing unit to actuator 184, the further progress of traveling member 182ec and its spacing units being arrested by their abutment upon the end of actuator Cc, upon the return of actuator 184 to normal rest position.

Now having filled a line of set or printed matter 10 with a requisite number of spacing units 182, the next step in the justification of the line consists in closing the channel 10 at its receiving end and in operating the justifying actuator Cc, for moving the spacing units into channel 10 between the words or phrases a distance sufficient to justify the line by means of the pressure of springs 182c of units 182. This necessitating first a complete understanding of the construction of traveling carriers 235, reference is herewith made to Figures 67 to 74 inclusive, wherein is shown a longitudinal channel 10 for receiving the said line of type or typewritten or printed matter, in individual characters or words or phrases, as required and a longitudinal slot 10a in its rear wall, through which the spacing units are respectively inserted and the line justification is accomplished. Channel 10 is or may be adjusted for lines of different lengths by means of stops 236 inserted in notches 237 situated at definite distances away from the receiving end of traveling carrier 235. The said stops 236 being provided with narrowed ends 236a for sliding into said notches 237 and forming a stop at the other end of channel 10. While the stop at the receiving end of said channel is provided by a spring-pressed member 238, pivotally mounted upon said carrier 235 at 238a and maintained in position by means of spring 238s abutting against a pin 238p on said member 238, a cross section whereof discloses it to be L shaped as in Figure 72, 40 with a vertical limb 238 and a horizontal limb designated 238c, at its free end provided with a larger L shaped member comprising a vertical limb 239, a horizontal limb 240, provided with a rear co-operative edge 240j for the accomplishment of the hereinafter explained purpose. As shown in Figures 71 and 74 part 239 has its vertical member 239 set a distance to the rear of vertical wall 238 of the spring-pressed member of the carrier 235. And as shown in Figure 73 a recess 10g is provided 45 for receiving part 239 and allowing its horizontal member 240 to move in a cut-out groove under the carrier 235 and beyond its rear edge, to allow of the co-operation of its cam edge 240j with a cam edge fixedly mounted at a definite point in the line of travel of the traveling carrier 235, to allow said spring-pressed part 238 to assume varying positions with reference to channel 10: firstly, to leave the receiving end of the channel open to allow of the shifting of set type or printed strips 50 into said channel; secondly, to close up the receiving end of the channel 10 by means of vertical member 239 of the L shaped free end of device 238 to allow of proper justification of the line, and justification accomplished and the justifying devices brought back to normal positions and out of operative connection with the channel, to allow of the extreme ingress of spring-pressed device 238 and pressure thereof upon the justified matter sufficient to maintain said justified matter in justified position for the further operations to which the said matter must be subjected to before it is returned by its traveling carrier 235 to its initial position, where it does or may co-operate with said stationary cam 1ax for pushing back spring- 55 pressed device 238 by pressure upon edge 240j, a

distance sufficient to allow of the ejection by gravity of the line of set or printed matter, with the next slight move restoring said member 238 in a position for receiving a new line of matter. The co-operative structure is illustrated in Figures 79 and 109, wherein the practicality of the structures shown must be apparent, the traveling holder 235 shown traveling in different directions, arriving first from its destination, the photoprinting machine C, at stop x of 1ax, with the spring-pressed device 238 still in its extreme compressed position and holding the set or printed matter in position in the channel. Then its further travel co-operating with nose cam 1 to push back part 238 its extreme distance for emptying the channel of its matter. The further movement bringing it to depression 2 where it is restored into receiving position, another step down to 3 places it into justifying position, and finally into position 4 and final locking position as it starts on its travel in the direction of photoprint machine focus, and so on. All of these latter operations, from the cutting off of the final word of the line, the justifying and travel and so on is or may be accomplished by the aforementioned lever 241. 25

The said lever 241 being provided with a handle 241a and is or may be pivotally mounted upon the machine at 241c, as constituting a short shaft, upon the inner end of which is attached an arm 241v, to which is pivotally connected link 254, the other end of which 255 is or may be in loose operative connection with one arm of a bell lever 256, said end 255 being arranged to move in a guide 263s of a guide structure 260. The bell lever 256 is or may be pivoted at 261, with its arm 259 slotted 35 and receiving a pin in the loosely connected end of link 254. The other arm of bell lever 256 being pivotally connected by means of a link 262 with a rocker bar device 268—269—270, at 263, the said rocker bar device comprising two arms—one at 40 either end, 267 and 266 respectively, fixedly mounted upon bar 270 journaled in the machine frame 1. From this rocker bar device are operated a number of structures of the machine, commencing with the cutting off of the last printed word or phrase and its shifting into the channel to the photoprinting of the printed line and so on and return to initial starting position—all accomplished by the one sweep of lever 241.

In Figure 76 is disclosed how arms 264 and 265 are pivotally connected by links 266 and 267 respective to other mechanical devices for the further operation of the machine. Important mechanical operations are carried out through link 266, the other end of which is pivotally attached to 55 rack 286 at 266p guided in its movements in slot 289 at end 266p and at its other end pivotally connected with other mechanism comprising means for pasting backs upon the justified strip of set or printed matter, as will hereinafter appear. Rack 60 286 being adapted to actuate the knife 186 for cutting purpose mentioned as an initial step and then, during the operation of the justifying actuator by means of link 267 for the justifying and releasing of the line to proceed to operate the 65 pasting mechanism for the purpose of pasting a back upon the traveling member 235 delivered into pasting position during a previous travel of the chain and sprocket carriage 228. The said carriage being preferably provided with a number of 70 separate carriers 235, three being shown in the present machine: one at the zone of setting or printing, the other at the zone of pasting, the third at the zone of photoprinting.

By this arrangement it makes it possible to 75

save considerable time and accomplish the work with expedition and efficiency, which would be impossible were only one carrier 235 to be employed upon the carriage. One carrier is filled 5 with a line of type or printed matter and is then moved by the carriage into its next position, which may be called the pasting position, where pasting may or may not be done, depending upon the kind of work required by the operator; the one that was in the pasting position being moved to the photoprinting position, while the third one that was at the photoprinting position having its contents photoprinted is returned to the setting position, to be refilled with matter for the others to go through their respective operations upon the completion of the setting or printing of the line in carrier 235 No. 1. The justifying being accomplished by the operation of device Cc through link 251 connected 20 with rack 277, arranged to actuate pinion 276 and thereby disc 275 to which is pivoted link 230L at 275e, the other end of which link is connected pivotally with arm 230 of device Cc, for operating same upon the completion of the cutting off process, shown in Figure 81, restoring said device Cc with its contained spacing bars to its extreme retreating position in alignment with carrier 182ec, for the restoring of the said spacing devices to the carrier, with one in actuator 25 184, and then to return to its normal rest position as shown in Figure 55. A shifting lever 279 being provided for shifting of the spacing devices from the justifying actuator Cc to carrier 182ec, before its restoration to normal resting 30 position. Lever 279 being pivoted at 280, connected by means of a link 282 with disc 283 arranged to be actuated by rack and pinion for the achievement of the shifting operation, as illustrated.

40 To reiterate, during the process of cutting off the completed strip, by means of the structures shown Figure 81 and the successive operation of the justifying mechanism Cc, rack 286, being in operative connection by means of a link with what I call pasting mechanism, proceeds to operate the said mechanism, as follows, where such work is called for. It being obvious that the structures by rack 286 for accomplishing the cutting off of the strip, are moved out of mesh 45 with operating pinions 287 and 288 shown when teeth set 286¹ and teeth set 286² have performed their operation of said structures 186 and 184, which by spring means 186sp and 184sp are respectively restored to their normal rest position 50 abutting on corresponding stops 186st and 184st respectively, while rack 286, through its link connection 358 proceeds in its course of travel to operate the pasting mechanism. The other end of said link 358 being pivoted to bell lever 355 55 pivoted at 355a, to one arm, while the other arm is connected by means of another link 356 with a rack 354 at 357; said rack 354 having teeth provided at various parts of its edge for the successive operation of the various structures 60 of the pasting mechanism; teeth 354a being first arranged to operate the tape feeding mechanism from a tape wheel 342, the tape 341 being fed by feed rolls 344 into the rear channel of carrier 235, through a chain 346 and sprocket 349 65 arrangement in operating connection by means of a shaft 345 with the feed roll 344, arranged to feed the tape through guides 347, through a guide 347a of anvil structure 10x, mounted by arms upon a rocker bar 364a journaled in supports 70 on the machine frame. Then, upon completion

of the feeding operation, by successive stages operating the knife 366—367 for cutting off the tape 341 and shifting it the requisite distance into the channel. Then comes the operation of the compressing mechanism for the pasting 5 of the paster onto the backs of the set printed or typewritten matter, for the making of a solid line of matter, which may be preserved for future use, in this particular class of work. The knife 366 is actuated by teeth set 354b coming into mesh with pinion 359 meshing with teeth 366t on knife carrier 366b arranged to move in guide 366g as shown Figure 101; the movement of the knife in a downward direction tending to move its cam extension 367 into slot 365 of anvil compressor 10x for shifting of cut off tape 341 a sufficient distance into the channel for performing the pasting operation.

Teeth 354a of rack 354 being arranged to actuate small pinion 352 for operating large gear 351, meshing with small toothed wheel 353, for operating sprocket 350, for moving chain 346, for actuating sprocket 349, rotating shaft 345 and actuating the feed mechanism through roll 344. With the final step in the pasting operation, the compression operation: This is accomplished by means of two compressor devices, an upper one 363, pivotally mounted at 363a and provided with a pressing head 10y, and a lower one directly underneath it, 364, pivotally mounted at 364a and provided with a pressing head 10x—or, to be more exact, heads 10y and 10x of the respective compressors being provided with arms 363 and 364 respectively, for mounting upon rocker bars 363a and 364a respectively, each journaled in supports on the machine frame, and arranged to be operated by a successive movement of rack bar 354, with teeth set 354c brought into mesh with pinion 360 in mesh with and arranged to actuate a device 361 having teeth, one end of which is linked by link 362 with compressor 10y through one of its arms 363, while said device 361 is itself pivotally mounted at 361a and at its inner free end mounted pivotally upon a cross arm 364cr by means of arm 361m 40 member thereof. So that it is obvious how by one pull upon part 361 both compressors, 10y and 10x are or may be moved toward each other, for the purpose of the compressing operation and 45 the pasting aimed at.

Having accomplished so many operations by successive stages through the operation of lever 241, we come to the movement of the sprocket and chain carriage for the delivering of the three line holding carriers 235 to their respective positions on the machine. As disclosed in Figures 55 and 85, lever 241 mounted at 241c is further provided with an arm 241d and another arm 241b, each having a specific function, in the course of the wide operative sweep of the said lever 241. Arm 241d being connected by means of link 241f to a lever 243 at 243e, the other end of said lever being connected by means of link 242 with slidably mounted rack 245, provided with blank and toothed segments for the operation of the sprocket and chain carriage and upon delivery of the three line carriers to their respective positions, with one of them delivered into the focus of the photoprinting machine, to continue its movement 60 a distance for linespacing the sensitized metal film or paper film and operating the shutter, for the photographing of the line of typewritten or printed matter presented at opening 30 of the photoprinting machine C.

It is conceivable that the entire series of op- 75

erations carried out by the single operation of the lever designated 241 has been or may be accomplished by a definite arrangement of the structural elements, so that they will operate their respective mechanisms consecutively without interfering with their individual functions, such as through a definite arrangement of teeth set on racks employed for the operation of parts. For example rack 245 is provided with toothless parts 245^{ts1} and 245^{ts2} and a teeth set 245^t and another teeth set 245^d. Naturally, to prevent the operation of the sprocket and chain carriage 228 prematurely and to allow of the completion of the aforescribed operations of the various mechanisms actuated through rocker bar arrangement 268—269—270, rack 245 must move along a definite distance with its teeth set out of mesh with pinion 187 operating the sprocket chain carriage 228; provision is made for that, as is seen in the drawings. Then to allow of the travel of traveling line holders 235, upon completion of the justifying operation, the spring-pressed member 238 must be allowed to lock the justified words and phrases in their justified positions, before starting on their trip. And before that, in order to perform the justifying operation, stop member 239 of device 238 must be allowed to enter a sufficient distance to operate as a stop for closing the receiving end of the channel 10. Teeth set 245 are arranged to serve that purpose, moving it from position 2 of cam edge device 1ax to end closing position 3 of said cam device, and with the justification completed teeth set 245^t taking up the operation of pinion 187 for operating the sprocket-and-chain 228 carriage to the end set forth. That done, teeth set 245^t move out of mesh with wheel 187, and its further movement operates line space wheel 248, maintained in position by a spring 248s and mounted upon a shaft 248R connected by means of a toothed wheel 312 with a traveling frame carrying a film or sensitized metal sheet or plate; said line space wheel being adapted to rotate the said shaft 248R for line spacing the film for successive line phototyping operations. The said line space wheel 248 being in loose operative connection with a line space lever 249 pivoted at 250 upon the rear end of rack 245, and being maintained in a normal rest position thereon by a spring 249sp and a stop pin 334; the spacing being adjustable by means of a device 333 carrying four arms arranged to produce variable line spacing—arm 1 for single spacing; arm 2 for double; arm 3 for triple spacing and the fourth arm for moving the line space lever entirely out of operative connection with the line space wheel, where phototyping is not required in connection with the operation of the printing and or typewriting and or setting machine.

The final step in the operation of the machine being the operation of the shutter by means of lever 298 connected therewith. This purpose is accomplished by arm 241b of lever 241 in its final movement before its arrest with the operation of arm 241j of bell lever 241v pivotally mounted at 241k, the other arm of which is or may be connected by means of a link 295 with a lever 296 pivotally mounted at 296a, the free end of which lever is connected with said shutter lever by means of link 297, to complete the round of structures controlled by lever 241.

Other means for line justifying is or may be provided for the machine disclosed in Figure 55 and so on, obviating the necessity for cutting the

strip of fed paper or metal between words or phrases. The machine embodying my inventions is provided with a series of keys designated 335, as constituting a V. S. or variable spacing keyboard, controlling the justification of lines of set 5 or printed matter, without the use of the complicated mechanical justifying devices hereinabove described in detail. The latter devices being controlled preferably from space bar 2s, as hereinbefore detailed, require no specially prepared copy to work from, because the justification is entirely automatic, performed by the operation of lever 241 after the aforescribed spacing units had been set during the writing or printing of the line by the operation of a 10 15 keyboard.

For justifying by means of V. S. keyboard, however, a master typewritten or printed copy must be prepared, displaying its ragged edge, the justification of the successive lines being determined by the space left at the end of each line, as measured by a graduated scale 340s on the face of line-holder 339 shown in Figures 97 and 98. The depression of a corresponding key 335 of the V. S. keyboard providing the proper justification of the line. For example, in Figure 97 appears a line of typed matter requiring no justification, in that it leaves no space at the end of the line. In Figure 98, however, a space equivalent to six notches on the graduated scale 340s 30 is left at the end of the line, with insufficient room for writing the next word "school" on this line. The line must, accordingly, be justified as it stands and the word "school" transferred to the next line. Now, for the purposes of the 35 citation let us assume that key 6 of the V. S. keyboard controls mechanism calculated to produce spaces of sufficient size to justify the line six notches shy of completion, as shown in Figure 98. So that depression of key 6 of said V. S. 40 keyboard will divide the six notches equally between the unit spaces of the line, for its complete justification. In like manner three notches left over space at the end of the line is or may be justified by a corresponding depression of key 45 3 of the V. S. keyboard; a space of eight notches controlled by justifying key 8, and so on.

The mechanism controlling the variable spacing of words comprising the aforementioned keys 335, numbered 2 to 10 inclusive, attached to key 50 levers 336 pivoted at 337, maintained by spring 336sp in normal rest position and restricted in its operative movement by stop 336st. It is or may be in loose operative connection with universal bar 194 of my machine disclosed in Figures 55, 56 and 85. The arrangement of parts and their relative operation may be clearly gathered from a casual examination of Figures 56, 90, 91 and 96. The central structure making it potentially possible to produce equal and variable 60 spacing between characters, between words and between phrases, constitutes a novel type of escapement or feed mechanism comprising a toothed wheel 190, fixedly mounted upon a short shaft 181r, at the other end of which is mounted 65 a feed roll 181, for co-operating with feed roll 181a to feed tape 183 a step at a time, of equal or variable size. The said tape 183 is or may be supplied by a spool 180 and is preferably wound thereon as in a spring-pressed tape measure, 70 controlled from a handle 180c. Wheel 190 is or may be arranged to be maintained in position by means of a spring 190s and to be operated by means of a loosely connected operating lever 192, 75 pivotally mounted upon a carrier 191 and main-

tained in normal rest position by means of a spring 196 and a stop pin 192p.

This construction of toothed wheel and lever described that allows of adjustment for either

- 5 equal or variable letter spacing, equal or variable word spacing, as respectively controlled from either keyboard KB, space bar 2a and/or keyboard V. S. aforementioned. Said feed mechanism 190—192 being controlled from keyboard 10 KB, which is or may be in loose operative connection with a universal bar 194 through hooked wires 195 as shown in Figure 56, of equal length and movement, for depressing the universal bar 194 an equal distance, for operating bell lever 194g, pivoted at 194ax and in operative connection with carrier 191 by means of link 193. This construction is adapted for equal character spacing as in typewriting. Where variable character spacing is required as is the case with printer's 15 type, the construction must vary somewhat in order to move carrier 191 a variable distance for operating the feed mechanism aforesaid, to produce a variable spacing between characters. This requires a type of construction as disclosed 20 in Figure 90, with the hooked wires 195 of different length and in variable positions with reference to universal bar 194, albeit of equal-distance movement. The hooked link 195(1) being arranged to depress universal bar 194 a distance 25 30 arranged to produce a larger character spacing, such as that required for wide letters such as m and w. Hooked link 195(2) a smaller space such as is adapted for characters like r, and 35 195(3), a still smaller spacing, such as is adapted for narrow printer's type such as the letter i.

Where special display spacing is desired, it is conceivable how an adjustable stop such as 253s interposed in the path of travel of carrier 191, may be adjusted by mechanism, a lever indicator or a key situated at the front of the machine for the achievement of such purpose. In Figure 91 it is shown adjustable by means of a screw 253c, in operative connection with a manually operated indicator lever 253—253t, pivoted 40 centrally upon an index plate 252. Any suitable character or word spacing desired may be obtained by manual manipulation of this lever indicator. This method of controlling the spacing between characters is of value where equal spacing of abnormal, irregular or display size is required for any predetermined purpose. But for regular character spacing the construction shown in Figure 56 is the proper construction, wherein a bell lever 3B1 is connected by means 45 of link 3¹ with key lever 3a and by means of link 3In with type bar 4, for performing of the feeding and printing operations by the manual depression of key KB.

By a similar arrangement and construction of parts as that shown in Figure 90, keys 335 of the V. S. keyboard are or may be arranged to produce a variable spacing between words for justifying lines of printed matter, such as demonstrated in Figure 98. Hook levers 338 (1, 2, 3) being in loose operative connection with universal bar 194 and arranged to depress it a variable distance, upon the operation of key lever 335 to which hooked levers 338 are severally 50 pivoted, and by virtue of their relative positions with reference to the said universal bar 194 arranged to produce a variable spacing between words, as controlled from corresponding keys 335 numbered 2 to 10 of the V. S. keyboard, outlined 55 hereinabove in some detail.

Space bar 2a being arranged to supply unit spacing between words, as for typewriting, the construction preferred shown in Figure 56. The index system is another efficient, although slower method of justifying lines of typewritten matter, as shown in Figures 91 and 94, already described in another connection, appertaining to character spacing. It is or may be likewise efficacious with variable word spacing, along the line of the V. S. keyboard method. By the adjustment of stop 253s at variable distances with reference to the inner end of carrier 191 by means of screw 253c, manually operated by indicator lever 253 the number of notches of leftover space at the end of a typewritten line determining the movement of the indicator to a corresponding notch upon the index 252 for producing the proper spacing to justify the line.

Another type of machine belonging to class 20 designated machine unit A in Figure 1, is disclosed in Figures 113, 114, wherein individual character stamping upon a tape 412 is employed as the preferred method of producing lines of type or matrices in one solid strip, unjustified or justified as desired, rather than in individual 25 pieces of type or matrices, or severed words hereinabove described. This effect is produced by means of a punch and die arrangement, such as shown in Figure 113, wherein a male and female stamping member are moveably connected with 30 one another and so arranged with reference to each other as to allow of the stamping of a corresponding character into the tape fed to said pair of members. A bar 395, preferably provided with a diehead 425 at its outer end is or may be slidably 35 mounted upon a guide 396, for slidable movement in and out of a common stamping position. A link 419 connecting said bar 395 with a bell lever 418 having a slotted arm 418c in loose operative connection with link 410 at one end 40 thereof, with the other end of said link pivotally connected with a key lever 409 maintained by a spring 422 and actuated by a key as in any ordinary typewriter. A bar 394, preferably provided with a punch-head at its outer end and carrying 45 a pair of raised letters, one small and one capital is pivotally attached to bar 395 at 420 and maintained in a definite position with reference thereto by means of a spring 420sp and a stop 421.

The stamping operation is or may be arranged to be performed by means of a power operated device 393, provided with a stem 397, carrying a shoulder 417, and moveable in guides 399 and provided with a compression spring 423 for maintaining stamping device 393 in normal rest position. It is or may be further provided with slots 393s in its sides, to allow of the feeding of the tape 412 for stamping one type or matrix at a time. The feeding of tape 412 is or may be 50 accomplished by feed rolls 415, with the tape supplied from a spool 411, and traveling between guides 413, 414 and 430, to maintain said tape in proper position for good alinement. The whole mounted upon a frame 432 arranged to 55 be shifted for stamping of capitals when desired; the said frame 432 being mounted upon a rocker bar 434 by means of arms 433, connected by a link 435 with a shift key lever 436, operated by shift key 437, for the purpose set forth. Stops 70 432st and 433st being provided to restrict the movement of the shift frame 432 in either direction.

The operation of stamping by power means being accomplished in the following manner: 75

5 Stem 397 is or may be provided with a flange 398 in loose operative connection with the forked end 402a of a lever 402, the other end of which is or may be pivotally mounted in its normal resting state in the lower end of a slot 416 and maintained in such pivotal position by specially constructed bell lever 404, pivotally mounted at 10 406 and connected by one arm through a link 407 with universal bar 408, arranged to be actuated by key lever 409 for the purpose herein set forth. Said bell lever 404 being provided at the upper end of its other arm with a cam slotted member 405 of such construction as to lift the pivoted end 403 of lever 402 to its extreme operative position when said bell lever is brought into operative position through operation of key lever 409 as controlled from a keyboard, and thereby allowing of the operation of forked lever 402 by the power-driven cam 400 mounted upon a 20 motor-driven shaft preferably, for the operation of stamping mechanism 393, for performing the stamping operations. With the releasing of the corresponding key, the operated structures return to normal rest positions respectively, bell 25 lever 404 carrying down with it the pivotal end of forked lever 402 to its normal rest position at the bottom of guide slot 416, from which position of rest, the motor-driven cam 400 cannot operate it, and springs 423 restore the stamping 30 device 393 to normal rest position.

35 In this machine justification of the lines stamped may be obtained by the V. S. keyboard method above outlined, a master typewritten or printed copy being provided for that purpose, and either raised or depressed characters being provided, arranged either for direct printing of a line at a time upon paper or other suitable material, or for casting lines of type upon delivery of the justified stamped line of matrices 40 to channel of the mould M of the casting outfit E shown in Figure 1.

45 By virtue of the construction of the last-described type of machine, with its power means for automatically stamping the characters successively upon the fed tape, it is obvious that its operation need be no less speedy nor efficient than that of a standard typewriting machine. It may be used alone as a stamping machine for the purposes set forth, or it may be used in combination with any or all of the machine units disclosed on Sheet 1, Figure 1, of the annexed drawings, or with any essential mechanical working elements therein contained. The justifying devices, the photoprinting machine unit, the 50 casting unit, the printing attachment B, and/or the drum D for regular printing. Employing the type of escapement or feed mechanism disclosed in the hereinbefore described machines embodying my invention, such as in Figures 55, 56 and 85, the arrangement and construction of parts may be such as to allow of the stamping of the printer's type into the strip of tape, or typewriter type, with variable or equal letter spacing adjustment 55 respectively obtainable as in the types of machines above described. With a V. S. keyboard attachment the proper line justification may also be obtained when desired by the operator, and the line of stamped matter may serve either the purpose of a line of type for printing purposes or 60 as a line of matrices for line casting purposes. This latter character stamping modification may be also commended because of its simplicity of construction, its efficiency and moderate cost of production, and moreover its compactness—it 65 being essentially no larger than a standard type-

writing machine, eliminating intricate, complicated structures from its mechanical economy, and massive, ponderous, expensive makeup, taking up large floor space and requiring constant attention of skilled mechanical engineers. In the 5 stamping machine embodying my invention all of the desirable and essential features are present and all of the undesirable, cumbersome, intricate and very expensive to manufacture and upkeep, are eliminated.

10 Another modification of machine unit A shown in Figure 1 is presented in a type of machine embodying my inventions, disclosed in Figure 112, wherein printed characters are delivered to a common point for photoprinting severally and 15 successively in words, spaces and lines, in a manner operated like unto the typewriter. With the difference that instead of writing each character by the inked impression of a type, each character is photographed upon a film 373F 20 carried upon a traveling carriage similar to that of a typewriting machine, and provided with an escapement or feed mechanism for letter spacing, spacing bar for word spacing, line spacing mechanism for equal or variable line spacing, as in the 25 abovedescribed machines and all the other appurtenances of the complete typewriting machines now in common use on the market.

20 The traveling carriage preferably comprises a pair of feed rolls 372—372a, upon which the film 30 is rolled and with which it travels during the feeding and line spacing operations, with the film 373F in back of the camera lens 373, adapted for photographing severally and consecutively the characters as they are delivered to the aforementioned common point 382 of the photoprinting machine C, being provided with a lighting means 376 for illuminating the character delivered to the common point, and mechanism for increasing or diminishing the focal distance of the camera 371, 35 40 for magnifying or reducing the size of said characters as desired. Said mechanism comprising a rotatable disc 375 containing lenses 390 arranged radially around its circumference, as shown in Figure 106, the said lens-wheel being 45 mounted for rotatable movement upon a shaft 378, upon the other end of which is mounted a toothed wheel 378t, in mesh with another toothed wheel 380t, in operative connection with an indicator lever 381, centrally mounted upon an index 50 plate 380, marked for different size type, from 8 to 28, each size type corresponding to one of the lenses 390 in device 375, which when rotated a distance, by the operation of said indicator 381 pointing to the desired marking on the index plate 55 380, will deliver into the focus the proper lens for photoprinting the size of type desired. For example, indicator 381 pointing to marking 12 of index plate 380, will rotate wheel 375 a distance to deliver the corresponding lens adapted 60 to photoprint twelve point size characters, into the focal zone. Indicator 381 pointing to marking 24 on the index plate 380, brings the lens 24 to the focal point for photoprinting 24 point size characters, and so on.

65 Assuming that the characters on the letter lever 383 are 12 point and that lens 373 of the camera 371 normally photoprints the successively delivered characters of that size. That for purposes of emphasis, a commencing character of a 70 line, or a paragraph is desired magnified to 24 point size, adjustment of wheel 375 by the indicator lever aforementioned is or may be arranged to produce the desired effect, and magnify it to 24 point size, for photoprinting the said display 75

character exactly that size. Where reduction in size is required, other lenses on the wheel mentioned, when adjusted as above described, are arranged to reduce the delivered characters to any desired size given by the lens wheel 375. With such provisions made for varying the size of the characters, it is obvious that the machine need be provided with but one font of type, or rather, printed characters on the head of the carrier 383, and the aforesaid means provided, of simple and inexpensive construction and arrangement, can serve the purpose of at least ten fonts of type, of different size and style, as indicated in the Figures 112, 106 and 108. Quite an advantage, from more than one point of view.

In the present modification of my machine, the characters are photographed individually and consecutively, as they are successively delivered to the common point 382, by the operation of key lever 385, which is pivotally mounted at 389, and is or may be in loose operative connection with a letter carrier 383, by means of a link 384, one end of which is pivoted to said key lever and the other end in loose operative connection by means 25 of a pin 384a with slotted arm 383a and arranged to move during its operative movements in guide 384g. The rear end 385r of key lever 385 is in loose operative connection with a universal bar 386—386a, which is operably connected by means 30 of a link 387 with the shutter actuator 388 and is or may be adapted for operating the camera shutter, upon the delivery of the required character at the common focal point 382 of the photo-print machine C.

Of course, it is obvious that a skilled operator, preferably an accurate typist must be assigned to do the work on such a machine, for it will brook of no errors, since errors cannot be readily corrected, or even detected until the entire 40 copy is developed and examined. When, of course, it will be too late to make corrections on a photoengraved metal sheet or plate, the errors of necessity being transmitted to the printed copy. Accuracy of operation is indispensable, 45 and if obtained in the shape of a perfect operator who makes no mistakes, then this is the most efficient printer's armamentarium to be desired, for it has all the good points of the best machines now on the market, multiplied by ten, 50 and is of simple and inexpensive construction.

To insure accuracy, an operator must work from a master typewritten or printed copy, the line justification being obtained by the application of the above principles as those disclosed in the 55 V. S. keyboard hereinabove described. And better still, to operate the machine by automatic means, such as indicated in Figure 112, wherein is shown a broken off arm 385at overhanging the key of key lever 385, for automatically operating 60 same from an automatic typewriter holding a master copy or stencil, from which it accurately and automatically transmits a perfect copy of the stencil contents, without any danger of errors being committed.

This arrangement requires an extra machine to automatically operate my machine shown in Figure 112 and a perfect master copy to work from. A novel attachment for automatically operating my machine disclosed in Figure 112 of the appended drawings, accurately, efficiently and speedily, I have provided as an essential related structural and functional element of the machine. The keynote here, too, being simplicity of construction, efficiency of operation and speed. 70 It is thought that I have achieved these results

by the application of the master copy or stencil principle in its most simple form, reducing the number of parts to a minimum and thereby rendering it more fool-proof than the machines of intricate construction.

The said novel attachment is disclosed in Figures 128, 129 and 130 of the annexed drawings and it is conceivable that the principle employed herein need not be confined to but photoprinting machinery, but may be employed also and more 10 so as an automatic typewriting machine of the class exemplified by the Hooven automatic typewriter. In Figure 128 is disclosed a bar 450 carrying a printed letter or more than one letter, adapted to be delivered to the common photoprinting point 382 of the photoprinting machine, for performing the photoprinting operation. Bar 450 being provided with a type or letter head 451, is pivotally mounted upon segment 500 at 453 and is provided with two arms, one 454, the other 455, 20 to the latter of which is attached a spring 456 arranged to actuate the bar 450 for delivering its letter head into the focus of the photoprinting machine, when pressure upon arm 454 is removed, or when retention bar 463 is moved out 25 of its normal rest position (1) and shifted to its releasing position (2). When the machine is not in use, it is this retention bar 463 that prevents the automatic spring operation of the series of type or letter bars, maintaining them in their 30 normal rest positions against the resistance of spring 456 which is arranged to severally operate them.

With, however, the operation of said bars required, the master sheet, 457 made of some tough 35 textile, fibre or metal sheet is adapted to maintain the said bars 450 in their respective normal rest positions against the resistance of their several corresponding springs. This it accomplishes by pressure, the said master copy 457 or stencil, 40 as I prefer to call it, being mounted upon two main rolls, 459 and 461 respectively and two auxiliary rolls 458 and 460 intended for guiding it in its movements, for operating the required bars. Roller 461 being provided at one end with a gear 465 which is arranged to operate it, said gear 465 being in mesh with a toothed wheel 466 arranged to be motor driven, for operating the roll 461, for winding thereupon the stencil 457, for bringing into alignment with corresponding arms 454 50 of bars 450, cut slots 463, numbered respectively 1, 2, 3, and 4, for example, for releasing the spring tension of spring 456, which through arm 455 actuates the bar 450 for performing the photoprinting operation by delivering letter head 451 55 into operative position with reference to the photoprinting machine C. Universal bar 462 being simultaneously released for operating the camera shutter, in a manner similar to that disclosed in Figure 112 and for allowing of operation of 60 the escapement, by the release of the usual means for locking same. The details, of course, being superfluous in connection with this machine, many of the structures being eliminated from the present disclosure and description, because no 65 novelty attaches to their structural or functional attributes, their construction and operation being common to the art.

The manner of operation by means of the stencil 457 being evident. The solid stencil tends to 70 depress arm 454 for retaining bar 450 in normal rest position against the resistance of a spring 456. But when the said stencil is moved and a corresponding slot 463 is brought into alignment with arm 454 of bar 450, the tension upon spring 75

456 is released, arm 454 swings into slot 463, when the said spring actuates the bar 450, for performing of the photoprinting operation. With the further movement of the stencil, as it continues to be moved across the arms 454, the end of slot 5 463 impinges upon said arm 454 and actuates it and forces arm and its bar 450 to return to normal rest position against the said spring resistance, likewise restoring the universal bar 462 to 10 its normal rest position against its spring resistance. And so on, the bars are successively and consecutively released when their corresponding slots upon the stencil are delivered into alinement with arms 454, and forced to return 15 to normal rest position by the continued progressive movement of the stencil.

It is conceivable that thus slots may be cut for 20 operating various levers controlling the line spacing mechanism for performing line spacing operations, and likewise for operating spacing devices for justifying lines of photoprintable matter, to eliminate ragged edge appearance, and so on, by judicious construction of the machine, with levers and parts provided on the machine 25 and so situated that the cut stencil or master copy can get at them in the abovedescribed manner, there is not a thing that cannot be done with the machine embodying my inventions as illustrated in Figure 112, through the hereinbefore described automatic attachment for operating type or letter bars, for respectively typewriting or photoprinting purposes as set forth herein.

With the completion of the detailed description 30 of the machines belonging to class A of Figure 1, let us proceed to describe line printing unit B.

Disclosed in Figures 1, 36, 37, 38 and 39, this machine unit comprises a line-of-type-holding actuator 11, provided with a channel 10P for receiving the type T and a member 11a in operative connection with means controlled from a keyboard, for performing the printing operations. Said means comprising a link 15 pivoted to 40 11a, by one end; the other end of which is pivoted to a bell lever 16, pivotally mounted at 17 and through a link 15a connected with power means controlled from a keyboard. The machine unit B is or may be provided with inking mechanism 45 comprising ink rolls IR, mounted upon a carrier IRL, held in apposition with a stop St by means of a spring Rs, said carrier being pivotally attached to a lever 117 at 117a, which lever 117 is pivotally mounted at 117b, and through its other 50 end linked with power operated means by link 118, for successively automatically operating the inkers and printing devices, for performing the printing operations. A platen 12 is or may be provided, to which strips or sheets of paper Pa 55 are or may be fed by feed rolls 120 and 120a, for coating with type holder 11 for performing the printing operations, the type entering into groove 13 of platen 12 for that purpose and a knife N 60 is or may be provided for the purpose of cutting off the paper into strips, for shifting said printed strips into the focal slot of the photoprinting machine for performing the photoprinting operations.

The automatic power-driven means for operating machine unit B comprising a rack 81af, embracing teeth set arrangements for successively operating the various structures of the machine, first the inking operation being performed, then the printing operation. A set of teeth 81th¹ 70 being meshable with gear 91a mounted upon and

arranged to operate wheel 92a, provided with a pin 92ab to which is pivoted one end of a link 15ab, the other end of which is pivotally attached at 15u to arm 11ab mounted on 11u, a bar journaled in supports in the machine frame; said 5 arms 11ab being attached to typeholding actuator 11 and arranged to operate same for performing the printing operations. The ink mechanism wheel 81bc being provided with a gear 92abc and a pin 92kf to which is pivoted link 18, 10 for operating the inking mechanism; rack 81af being provided with a row of teeth 81th on its other edge meshing with a toothed wheel 87a mounted upon a short shaft 86a¹, upon the opposite end of which is mounted another pinion 15 86a, part broken away, the two wheels being mounted upon a carrier 83a, adapted to move wheel 86a into engagement with motor-driven gear 85a, mounted upon motor shaft 90a, for operating the rack and thereby the aforementioned structures connected operatively therewith. The said carrier 83a is or may be provided with a slot 83s¹ for receiving the cam end of a shift, situated at the front of the machine, such as 89, shown in Figures 30 and 32. 25

Machine unit B, as a line printing machine, may receive its line of set type from a machine of the construction disclosed in unit A of Figure 1, where individual type is set and delivered into the type channel of the type actuator 11 of machine unit B. Or a solid line of stamped characters, justified or unjustified, such as may be made in the machine embodying my invention, disclosed in Figures 113, 114, may be shifted into said line printing machine B, for performing the 30 printing operation. The printing may be done on regular standard sized paper, such as 8½ by 11 or 13, and printed, line by line, until an entire page had been printed, as with any typing machine, where individual characters are written, 35 to produce, of course, better and more uniform printing than is possible with the individual character printing. Or the printing may be done on strips of tape, in justified or unjustified lines, to be shifted into the focal slot of the photoprinting machine, for performing the photoprinting operations. 45

The main object of the present combination of typographic machines is not alone to produce the novel and useful, but also and more so to simplify and reduce the number of operative parts to a minimum, and wherever possible to eliminate superfluity of operation by reducing double processes to a single process. This refers to the negative and positive of the photographic processes, wherein the initial step is to take a negative and then convert the negative into a positive by means of a photoprinting machine. In the present invention of mine, the negative process is eliminated, a positive being directly produced upon a sensitized sheet of paper, or metal. 50

The method employed for the production of such result is simple and quite easy of comprehension. The characters are preferably printed in white on a black background, which has the 55 effect of making a direct positive on the sensitized paper or sheet of metal or metal plate, and eliminates the double process photography and the consequent double developing—first, of the negative and then of the positive. The photograph of each line taken direct upon the metal sheet, when developed, produces the photoengraving, ready for the printing drum D, or any other suitable printing apparatus, for performing 60 printing operations in volume. It would be su- 70

75

perfluous to go into a detailed description of the photographic process and the method of developing the photoprinted sheet of metal, or entering upon an erudite discussion of the suitable developing solutions employed. Being concerned primarily with construction, arrangement and operation of parts, it behooves me to proceed with the further description of the structure of this photoprinting machine C, of which several modifications are shown in the annexed drawings.

The type disclosed in Figure 1, unit C, and shown in sectional views in Figures 43 to 54 is provided with a camera 100, comprising a lens 163, with a projection 101 with shutter mechanism housed therein, the shutter 102 having an opening 101j, normally out of alignment with the focal opening of the camera, brought into alignment therewith by means controllable from a keyboard, for photographing the printed line delivered. Shutter 102 being connected by means of a link 102a and a lever 102b with said controllable means for the purposes set forth. A slot 27 is or may be provided for introducing the film into the camera 100, lamps 28 being provided for illuminating the work, and keys, numbered eight to twenty-four are or may be provided for moving the camera or the work a distance away from each other for increasing or diminishing the focal distance, magnifying or reducing the characters presented for photographing. A simpler method for the achievement of the same purpose has already been described in connection with the machine type disclosed in Figure 112, and Figures 106, 108, 110 and 111.

The manner of magnifying or reducing characters by the method disclosed in machine unit C of Figure 1, comprising a keyboard KF, embracing keys numbered 8 to 24, corresponding to size or points of type, in operative connection by means of key levers 3a with either a hooked or forked lever, 108j or 108 respectively, for moving a universal bar 113j or 113 respectively to shift the camera or work for the purpose set forth. The said levers 108 being pivoted to a bell lever a, operably connected by means of a link 111 with key lever 3a, the operative arm of the said bell lever being of variable lengths corresponding to the key with which it is in operative connection, for moving the forked lever a distance varying with the size of type desired to be photographed; depression of any key Kf being arranged to lock said key against return movement, by means of a cam member 3b, coacting with a rocker bar 106a arranged to move by spring tension into recess 3cd for performing the locking operation and the photographing of all characters delivered to the focal channel, the size indicated upon the locked key. The unlocking being performed by means of an arm 104 mounted upon rocker bar 107, when the size of the type is to be varied, with the depression of another key.

In Figure 43, camera 100 is provided with a slot in the back thereof, 162a, in a removable plate 162, the said slot opening onto a space of film upon which the photographic impressions are to be made; this said slot being diametrically opposite to and in alignment with the focal slot 30 of the photoprinting machine C, to the front of which the line of printed matter is delivered for photoprinting purposes. The film being arranged to move along a channel 161, until the entire page or column is photographed

thereon, when by automatic means it is caused to descend into a developing chamber where it is or may be arranged to be rocked and swayed by a rocker device 164t through arm 164 linked thereto by one end and by the other to a revolute plate arranged to be driven by power means, for the purposes set forth. And the means for line spacing the film being of the construction and arrangement of parts hereinbefore fully described, in connection with the machine disclosed in Figures 55 and 85. Cross sections at A—B and C—D disclosing respectively the inner face of the front of the machine and the front face of the film plate and their respective means of arranging the matter and moving the film frame. In Figure 48 is shown a capital W exposed, with the rest of the line of character covered up, for the purpose of magnifying that character as a display character, to about the size disclosed in Figure 49, with the rest of the characters subsequently photoprinted in normal size. The enlargement being carried out by either of the above two methods, described in detail. The travel of the film frame and the film being procured by a chain 161 and sprocket 167—168 arrangement, the same being in operative connection with power-driven means. In Figure 54 is disclosed another method of feeding the film 170 between feed rolls 171—172, instead of by means of a frame or plate.

A fairly good idea of the construction and operation of the photoprinting machines C disclosed in Figure 85 and others, of the annexed drawings, has been hereinbefore given in connection with the description of the manually operated lever 241, shown in Figures 55 and 85, so that it would be superfluous to repeat it at this juncture, confining our attention only to such structures and arrangements of parts as have not been fully explained heretofore. For example, in Figure 48 is disclosed the method for exposing a potential display character, such as W for enlargement, individually, apart from the rest of the line of printed matter delivered into the focal channel for the same purpose of photoprinting. The W, therein designated 30ch, first exposed, while the rest of the characters are covered up by cover 29, is subsequently covered up by cover 30t, and cover 29 removed, for the exposure of the remaining characters and the readjustment of the proper focal distance for photoprinting of the remainder of the line in their normal size, as shown in Figure 49. Like provision, for exposing an opposite part of film must be made, such provisions, requiring no special ingenuity and constituting no radical change, not being taken up in detail herein. Of course, in my machine, shown in section in Figure 112 and further and other figures on sheets 13 and 14 of the annexed drawings, such exposure and cover arrangement are dispensed with, because of the individual presentation of single characters successively and consecutively to a common focal point for the purposes hereinbefore set forth. And as to enlargement and reduction of any one or any number of characters delivered to the common focal point, the mechanism for such purpose and its manner of operation has already been fully described in the preceding pages.

As described above, means are provided for adjusting line-holding channel 10 to receive lines of printed matter of varying lengths, by means of stops 236 inserted into set notches 237 of traveling carrier 235. Corresponding adjustment for the size of the focal slot, in accordance with the size

of the line to be photoprinted, is provided for, as shown in Figure 55, in a slide and graduated scale arrangement, preferably. Slide 251 being arranged to move in snug-fitting grooves, a distance into the focal slot, sufficient to adjust such slot to a length corresponding with the length of the printed matter delivered for the purpose of photoprinting.

In connection with the description of the focal adjustment wheel 375, shown in Figure 106, it must be here added that the said wheel is provided with a hole 6 normally in alinement with the camera lens 373, to allow of unmagnified or unreduced transmission of the image to the film, the delivered character being photographed natural size, preferably by the camera lens arrangement, a short focus lens being of necessity used for such purpose, to allow of compact arrangement of the parts of the machine. Other structures relating to the adjustable focal length mechanism appear in Figures 110 and 111, wherein provision is made for locking the indicator 381 against movement away from a set point for the purpose of adjustment of a desired lens on wheel 375 in alinement with the camera lens for the purpose set forth. These structures, comprise a spring-pressed pin 394 in handle 395, of indicator 381 rotatably mounted at 381a, the said pin being arranged to move into a corresponding hole 393 in the index plate, for the purpose set forth.

The manner of delivery of the film to the developing tank for the purpose of developing in suitable solutions contained therein has been briefly outlined above and is shown in a crude plan view drawing in Figure 50. Let that suffice to supply the idea of film transmission from photoprint machine C to the developing tank Tk, and the automatic mechanism for effecting that operative movement from power-driven sources 40 is or may be linked with the power driven mechanism for automatically operating the rest of the machine elements hereinabove described partly in connection with the operation of the line printing machine unit B, as controlled by a switch 45 89e, or 89t, hereinafter more fully described in connection with other elements, when the operation of the machine as a whole is taken up. One means of developing of the film as far as the 50 mechanical features of the work is concerned has already been described above in connection with the machine shown in Figure 43, wherein provision is made for moving the film back and forth, up and down in a swaying movement, stirring it in the solution, for producing the proper development of the photograph.

Another method is disclosed in the machine shown in Figure 85, wherein the chamber Tk is provided with a moveable table 303, to which the film plate is delivered; said table being provided 60 with feet 316, provided with roller bearings or casters 316a in their free ends, arranged to fit in and move along grooves 331—332 in the walls of the tank Tk, carrying the table 303 up and down along said grooves, for first introducing the 65 work to be developed into the solution, in its movement from its rest position down into the solution 304 along vertical grooves 331 and then moving table 303 and its work thereon, up and down in oblique grooves 332 up and down, for 70 producing that swaying back and forth movement of the work in the solution, as a prerequisite to proper development of the film. Without further provision, the tendency on the part of the operative power-driven mechanism would be to 75 move the work into and out of the developing

solution as the table would be carried up and down the entire length of the vertical and oblique grooves aforementioned. Provision, therefore, has been made, for retaining the work underneath the surface of the developing solution, for purposes set forth, after the table had been moved into the solution along the said vertical grooves 331, and the subsequent up and down and to and fro movements confined to movement up and down in the oblique grooves 332 by the automatic 10 power driven means provided for that purpose.

This purpose is effected by a foot lever 305 preferably, such as shown in Figure 85, said lever being provided with a foot disc 305m at its outer operative end, is mounted at 306 for pivotal movement upon a support attached to table 300, and comprises an inner free end 306t, maintained in normal rest position by a spring 305s; the said free end 306t being connected by link 307 with lever 307c, pivotally mounted at 307p, the other end 20 of said lever 307c being pivotally attached to table 303 at lugs 303c. The said lever 307c shown in the drawings designated Figure 85 constitutes practically one of two arms, one on either side of the said table, fixedly mounted upon a rocker bar 25 307n, journaled in the tank frame, and depression of foot lever 305 causes link 307 to operate the said rocker bar arrangements for lowering the table and the work thereon into the solution, to lock the said foot lever against complete return movement up the vertical grooves 331, confining its potential movements to the oblique grooves 332, by means of a spring latch 327, which so locks and allows of its restricted return movement upon removal of the foot from the lever 35 disc 305m. As shown in Figures 86 and 87, lever 305 is provided with an extension 305x, arranged, in its descent to operate latch 327, move beneath it, allowing the spring-pressed latch to return by the pressure of its spring 328 into normal rest 40 position, to prevent the return of the foot lever to its normal rest position.

This arrangement makes it possible for the power driven machinery to take up the development of the film as set forth, in the following manner: by operating the rocker bar structure 307c through link 307 and moving the table and the work up and down, to and fro, from side to side in a swaying movement, along the oblique grooves 332 only, and within the confines of the developing solution. An arm 322 being provided for that purpose, comprising a U shaped free end 324 as shown in Figure 85 in loose operative connection with the said link 307 by means of pin 324g, its pivotal attachment to the rear end of the foot lever 305. Said arm 322 being pivotally mounted 50 at 323, operably connected by means of link 321 with a revoluble disc 325, one end of said link being pivotally attached to said lever arm 322, the other end of said link being pivoted to said disc 55 at 325p; the said revoluble disc being in operative connection with a motor-driven wheel by a system of gearing tending to reduce the speed to a suitable number of revolutions per minute for performing the operations set forth, in the development of the work. For which purpose, a large gear 318 meshes with toothed wheel 326 operably attached to wheel 325 and arranged to 60 revolve it at reduced speed; said gear 318 being also in mesh with gear 317, with the latter arranged to operate the former; 317 gear in mesh with gear 85 mounted upon the motor shaft, and arranged to be driven thereby, for driving the 65 system of gearing, for operating arm lever 322, for moving rear end of lever 305 up a definite 70 75

- distance predetermined by the attachment of link 321 to disc 325 at a definite point thereupon 325p, to allow of the movement of the table feet casters 316a down the oblique grooves 332, to the lower ends of said oblique grooves 332, when, by the action of disc 325, arm lever 322 is made to return to its normal rest position, to allow of the automatic return of the rear end of foot lever 305 to its normal restricted position aforescribed, by the tension of its own spring 305s, for carrying the table back to a position underneath the surface of the developing solution, with its casters 316a in the upper ends of the oblique grooves, further movement upward being prevented by latch lock 327, as aforescribed. And so on, the movements of the table are or may be effected for a predetermined period of time sufficient to develop the film, and then by an arrangement disclosed in Figure 85 switch off the current to stop the motor operations, upon release of foot lever 305, to allow it to return to its full normal rest position, a switch sw being provided for that purpose arranged to turn on the current and the power, when the foot lever is depressed and moved into its restricted rest position, and to shut it off and stop the operation of the motor, when foot lever 305 is released and allowed to return to full normal rest position.

The predetermined duration of time for development and operation of the power-driven mechanisms, being controlled preferably by the movement of a rack 319, in mesh with wheel 318, of slow speed movement, so adjusted that the time taken up with one revolution thereof shall be sufficient to move the rack a distance to cause its pin 320p to operate switch sw for shutting off the power and for ceasing its further operation of the means for actuating the developing apparatus, when the development of the film is or may be complete, and the film is ready to be removed from the tank. By a like arrangement of structural elements, the developed work is or may be automatically removed from the tank Tk and moved into a drying compartment, from which it may be removed by the operator, a finished photoprint or photoengraving, ready for whatever other purpose it is or may be intended to serve. Such structural elements have been disclosed and briefly described in connection with Figure 43, wherein was shown the method of development and its manner of travel to and fro, up and down track 161, to be returned to compartment, Ch, where it may be allowed to dry and removed through an opening in the side of the machine.

In the preceding description of photoprinting structure and operations, we dealt with either individual character photoprinting, or single line photoprinting at a time, when either the single character or line of printed matter was delivered to the focal slot of the photoprinting chamber. However, I have provided means connected with the photoprinting machine C that allow of the photoprinting of an entire page or column of type-written or printed matter, either in its entirety, which is no novelty to the art of photostatting, or line by line, automatically, which is new to the art, line after line being successively fed automatically to the focal slot of the chamber, with simultaneously fresh lines of film being fed automatically for receiving the imprint, until the entire letter sheet of typewritten or printed column, is completely photoprinted upon a paper film or sheet metal sensitized for producing a photoengraving, to serve required purposes. This method

is a radical departure from the practices common to the photoprinting art, and has its advantage in requiring a small inexpensive camera to accomplish the work of the large ones, and in making it possible to enlarge or reduce certain characters, lines, words or phrases, as required, in a manner hereinbefore outlined.

This automatic type of photoprinting is or may be accomplished by means of an attachment in the very same photoprinting chamber C, which is normally arranged for the class of work hereinabove described. As shown in Figure 123 of the appended drawings, line space wheel 248 is mounted upon one end of shaft 248R and is adapted to rotate said shaft, at the other end of which is mounted another toothed wheel 312, meshing with a toothed edge of the film plate 315; the said toothed wheel 312 being in this new arrangement made to serve the purpose also of a line space wheel, in loose operative connection with a line space lever 441, pivotally mounted upon a slide bar 439, the said line space lever 441 being spring-pressed, all, similar in structure and operation to the line space mechanism at the other end of shaft 248R. The slide bar 439 is or may be connected by means of link 444 with a revolute disc 446, being pivotally mounted upon a pin 445 thereon. A gear 448, shown in broken lines being arranged to revolve said disc, is in mesh with a motor-driven wheel 3047, mounted upon the motor driven shaft 441a, from which the operation of the said described mechanisms may be started by a switch not shown and maintained during the duration of the successive line photographing, until the completion of the work, when the operation is or may be made to automatically cease, by a like method as that above described, and the photoprinted film delivered into the developing chamber for the purpose of development, and so on. It is conceivable that during the movement of slide 439 by the revolute movement of disc 446, the line spacing operations are effected to successively deliver a fresh printed line to the focal channel and fresh surface of the film sheet upon which the imprint is to be had. Like means as those above described being provided for variably spacing the work and simultaneously the film, or for entirely moving the line space lever out of operative connection with the line space wheel 312. Upon slide 439 is mounted a pin 440 which coacts with a spring pressed lever 438 to operate the shutter lever 298 and the shutter, through a connecting link 442, during the movement of said slide in its operative direction, said lever being released upon the return of the slide to normal rest position and is returned to its normal rest position by means of spring 443. So that it is seen that that operation is entirely automatic and consists of successively line spacing the matter and opening and shutting the shutter for photographing the matter during exposure and resting during the feeding of the printed line and the film by the line space mechanism. The which brings us to machine unit D.

Nothing much to describe here, this element being included to merely show a complete printer's armamentarium, and how the line of type, justified or unjustified is or may be shifted from its set line holder to the drum for performing the printing operations, after the required number of lines had been set. With the final machine unit to describe, namely: casting unit E: comprising a melting pot MP and a line casting mold M, which is arranged to receive metal under pressure from the said melting pot, comprising a plunger P, 75

to the outer end whereof is pivotally attached one end of lever L, pivoted at L₁, the other end of which lever L is pivotally attached to one end of link L₂, the other end of which is pivotally attached to revoluble disc 92 at 93, all arranged to operate the plunger P for filling the mold M and restoring the said plunger P to normal rest position, during one revolution of said disc 92. The metal from the melting pot is or may be forced through a channel 22 of pipe 20 into a rectangular chamber 21, provided in its front wall with holes 19 through which the molten metal is forced by the pressure of plunger P, into mold M, for casting a line of type.

15 The mold M comprises a rectangular chamber open in the rear for receiving the metal poured into it through the holes 19 in the front wall of chamber 21 connected with the melting pot, and provided with a matrix-holding channel 9a, into which the line of matrices are delivered by suitable shift mechanism, such as has been hereinbefore described; the said channel 9a being covered in front by plate 17. Switch 9s¹ mounted upon the outer end of a rotatable member 9s² is arranged to move a stop or shutter 9s, mounted on the inner end of member 9s², into a position to close the receiving end of the mold, after the matrices have been delivered into the mold channel, for performing the casting operations, a detent spring sp being provided to maintain stop 9s in its delivered position. Shifting device 6 controls the switch 9s¹ for locking the mold channel, through ejector 156 coaxing with toothed wheel 9w for operating said switch 9s¹.

35 Mold M being pivotally mounted upon frame 69 at H₁, and is arranged to move along the front face of said frame, into operative casting position and into operative ejecting position. The movement is accomplished preferably by means 40 of gearing—one gear 78 mounted at H₁, and the other gear 79, meshing therewith, mounted upon H₂, a rotatable shaft, in operative connection with the power driven means for operating the gear 78, for moving the mold into and out of the abovementioned positions respectively.

45 Knives 64 are fixedly attached to the front face of frame 69, in a position to allow of the trimming of the cast metal as the mold is moved by the aforementioned means in the direction of its 50 ejecting position, shown in Figures 23 and 27, along a maintaining arcuate guide 63, for maintaining the rear edges of the mold in close apposition with the face of frame 69, which is or may be provided with a slot 66 and a lower receiving cabinet 68, for receiving the slugs of type: the inner edge of slot 66 comprising a pair of T slots for receiving the T shaped ejectors 60 during the ejecting operations.

55 Ejectors 60 are or may be mounted for slidable movement in frames preferably on the upper face of the mold, in frames 61, one frame to each of two ejectors; said ejectors comprising a rectangular part 60, provided with grooves 10b at its outer end for receiving the forked ends of the 60 ejecting actuator 69K, for performing the ejecting operations, and T shaped rear part 60a, arranged to occupy slots, one to each ejector, in the upper wall of the mold, and to move therein for ejecting the cast slug 18 during the ejecting 65 operations, and to fill in the slots during the casting operations. The T shaped part of the ejector 60a, being provided with a heel 60b which is arranged to descend a short distance into the mold chamber, while the rest of the lower edge of the 70 75 T shaped part 60a is flush with the inner face of

the upper wall of the mold. To the end that the heel 60b makes a depression in the cast slug, sufficient to allow the heel to push the slug 18 out of the mold during the ejecting operations, and into a receiving compartment through slot 66 in frame 69, the said T shaped parts of the ejectors moving into the T slots 67 respectively, for guiding the movements of the ejectors during their ejecting operations.

Which operations are performed by means of 10 an ejecting actuator 69K, mounted preferably upon a rocker bar 72 by arms 71, and at its free end provided with forked ends 70—70a, the prongs of the fork being arranged to be received into the grooves 10b of each corresponding ejector 60, 15 when the mold is delivered into its ejecting position, with the mold chamber in alinement with slot 66 and the T ends of the ejectors in alinement with T slots 67. The said ejecting actuator 69K, being in operative connection with power-operated means, arranged to perform the ejecting operations after the melting pot had been operated for forcing metal into the mold, and the mold moved upon its pivotal axis and brought into the ejecting position. The said means for operating 20 the ejecting actuator comprising a link 74 one end of which is pivotally attached to said actuator 69K at 73, the other end to an arm 95 of a rocker bar device 97, which is provided with another 25 bar 94 mounted on the other end of rocker bar 30 97, which is spring-pressed, maintained in a normal rest position by means of a spring 91; the said other arm 94 occupying a position lying in the line of travel of an arm 81n on operating rack 81, which arm 94 is arranged to actuate the rocker 35 bar device 97 through said arm 94, for operating the ejecting actuator, for performing the ejecting operations.

Means being provided for allowing of the discharge of the line of matrices from the matrix 40 channel 9a, by means of gravity into a channel 9ab in frame extension 69E. This is accomplished by opening the other end of the channel 9a automatically when the mold reaches its ejecting position, through the operation of a spring 45 pressed device normally functioning as a stop for the outer end of the channel 9a. This device 15 comprises a spring-pressed plunger part 75, provided with a spring 75s, a stop part 76, a slotted member 77, having a stop abutment 77a, for arresting its movement against the resistance of said spring 75s. Said device 75 being arranged to move in a guide slot inside the outer end of mold M, normally serving as the stop or outer wall for the matrix line. When the mold is 50 moved into ejecting position, the spring-pressed member 75 is made to abut against the frame of the machine 1, and is arranged to bring its slot 77 into alinement with channel 9a, when the mold reaches its ejecting position, with the 55 result that the line of matrices drops by gravity into receiving channel 9ab, and the mold returned to its casting position ready for receiving a new line of matrices and to go through another casting operation.

60 The power operated means for automatically operating the casting unit is, like the means hereinabove described in connection with the other machine units, performed by successive and consecutive operations of the various mechanical devices by teeth sets in a gear-operated rack, controlled by a switch at the front of the machine. Such as 89, provided with a detent spring for maintaining it in a set position to which it had 65 been delivered, is mounted upon a rotatable bar 75

82, provided at its other end with a cam device 82_k, housed in a slot 83₁ of a carrier 83, on the other end of which is mounted a pair of wheels, 86—87 respectively, the former arranged for meshing with the motor-driven wheel 85, and the latter, with rack 81. With the switch 89 in operative position, wheel 86 is delivered into mesh with motor-driven wheel 85, and through its wheel 87 actuates the rack 81 for successively actuating all the structures therewith connected, as fully set forth and as illustrated in the accompanying drawings in Figure 30. It is obvious that during the movement of said rack 81, teeth set 81_t will first operate toothed wheel 91 and therefore revoluble disc 92, for operating the melting pot MP for performing the casting operation, with the means for moving the mold upon its axis unoperated until the casting operation had been performed, a blank part of the rack 20 being in apposition with wheel 88 controlling wheel 88 in mesh with mold gear 78, until teeth 81_t are moved into mesh therewith as described after the casting operation had been performed, when wheel 91 is released and wheel 88 is operated, for moving the mold into the ejecting position and performing the ejecting operation, against the resistance of a spring 80 sp, which tends to restore the mold to normal casting position, upon release of wheel 88 by teeth 81_t, when blank 81_b is reached; the switch being then automatically restored to normal rest position, to allow of the disengagement of its actuating members from the motor-driven wheel, and the return of the rack by spring means to its normal rest position, without operating the structures lying in its path of return travel, some of the parts not shown in Figure 30 of the accompanying drawings.

A preferred method for automatically operating the various mechanical devices of the machine units, is shown diagrammatically in Figure 124, wherein a carrier 450, slidably mounted in slide grooves 453, carries toothed wheels 455—456, revolubly mounted on its operative end and connected by means of a sprocket and chain device, so that operation of one of said toothed wheels, such as 455 is transmitted to the other wheel 456, in mesh with a gear shown in broken lines, 459, which it is arranged to operate and through 50 it, a revoluble disc 458, connected by means of a link 464 attached to said disc by one end at 465, with a slidable carrier 449a, carrying an actuator 449, having a cam edge 466, in loose operative connection with a series of actuating levers—468, 469, 470, respectively pivoted at 468x, 469x and 470x, and respectively provided with actuator arms 468a, 469a and 470a and link arms to which are pivotally attached, respectively links 473, 472 and 471, connected with various parts 55 of the actuating structures of the machines, for successively operating same by the release of a switch such as 89, causing it to move its wheels into engaging position with reference to motor-driven wheels 457 and disc driving wheel 458, the former for being operated, for operating its mate 456, for operating disc 458 and through link 464 moving slide 449 across the path of the aforedescribed levers, for operating the various structures in operative connection with them, then to return 60 the slide to its normal rest position and automatically restore the switch to its normal rest position, the disclosed three levers being arranged to return to normal rest position by spring means shown. The restoration of the switch being effected by means of a one-way actuator 460, piv-

totally mounted at 461 and arranged to be maintained in normal rest position by means of a spring 467 and a stop pin 462. To the end that during the course of travel of slide 449 in its operative direction one-way actuator 460, impinging upon arm 82t of cam end of switch-bar 82, is arranged to be itself actuated against the resistance of its spring 467. However, on the return trip of slide 449, one-way actuator 460 having been restored to normal rest position by its spring 10 means, meets with the resistance of arm 82t of switch bar 82 and now, being itself fixed and unmoveable, tends to move arm 82t a distance sufficient to cause it to restore the switch to its normal rest position and to bring cam 82k into 15 a position to allow of the disengagement of wheels 455 and 456 from their respective structures, by the action of spring 451. Which is believed to be a more efficient means for automatically performing the various operative functions of the 20 structures of the machine, as hereinbefore set forth.

In Figure 112 was shown extraneous means for automatically operating my individual letter photoprinting machine, with only a broken off end 25 of a bar 385_{at} of the automatic extraneous machine shown to indicate the manner in which my photoprinting machine may be operated automatically to promote accuracy of operation and perfection of result. But in my machine as disclosed 30 in Figures 130, 129, 128 and 133, I have provided a novel and efficient means for automatically operating the photoprinting machine for performing automatically the photoprinting operations, or for the purposes of automatic typewriting. 35

In my novel and efficient automatic typewriting or photoprinting machine the number of parts are reduced to a minimum, with the keys and key levers and links and cams and wheels, and so on, all eliminated, and with only the type basket 40 left, with a series of type bars or letter bars 450 remaining, radially arranged and suspended from a segmental support, 455_{Sg} with the bars severally hanging down and arranged to be pivoted in a direction upward and backward toward the 45 common writing or photoprinting point, by means of a spring 456, or other suitable power means, normally held in rest position by a stop bar 463_{st}, of common use in the art, which is arranged to be moved out of the path of travel of the bars when 50 the machine is in operation.

The bars are so constructed that when the stencil 457 is inserted in the machine and wound taut on the rolls—459, 461, 458 and 460, the type bars are severally retained in normal rest position 55 against the resistance of a spring 456 arranged to operate the bar 450 when its arm 454 is released, stop bar 463_{st} being moved out of the path of travel of the bar. The said bars 450 are or may be T shaped, provided with a cross 60 bar on top, comprising two arms, one of which 454 being in loose operative connection with the said stencil 457, made of tough material or sheet metal, tends to maintain the bar in its inoperative position until it encounters an alining slot 463 in 65 the stencil, when the pressure upon arm 454 being released, spring 456 actuates bar 450 for performing the writing or photoprinting operation, by tension upon the other arm 455, arm 454 instantaneously moving into slot 463 of stencil 457, en- 70 countered in its path of travel to allow of the swing of the said bar 450, and as the stencil continues its movement, the end of the slot abuts against the edge of the said arm 454 and actuates it, for restoring the bar to its normal rest 75

position as arm 454 is pushed back into its normal rest position against the action of spring 456 and is again covered and maintained in its inoperative position until it encounters another corresponding slot in the course of travel of said stencil, when the same operation is repeated.

It is obvious that a slot definitely situated in the stencil corresponds to a bar intended to be operated when the said slot reaches a position over and in alignment therewith, to allow of the movement of arm 454 into said slot, for releasing spring 456, for actuating the bar 450. Thus each slot appearing on the stencil 451 is intended to allow of the operation of a corresponding bar, for the phototyping or the typing of a corresponding character. The type carrier or letter carrier being provided with a type head 451 is arranged to swing in the direction of the common point, to coact with other means as shown in other machines embodying my inventions for which I hold Letters Patent, Nos. 1,417,489; 1,389,237; 1,403,836—the last mentioned being provided with a novel inking mechanism, for automatically inking the types as they are successively delivered to the printing point, and for performing the printing operations.

For phototyping purposes, however, coacting structures are unnecessary, for the head of the bar carries preferably printed characters, which the bar moves into the common phototyping position or focal slot, 382, for performing the phototyping operations, as herein set forth. For operating the carriage P, of an automatic typewriting machine, or for operating the carriage 372 of the phototyping machine C I have provided rocker bar mechanism, likewise arranged to be automatically operated by means of a spring or other suitable power, for automatically operating the escapement and the camera shutter successively, for feeding a new surface of film and transmitting the imprint thereupon of the letter delivered to the focal slot in the machine. Of course, the operative connection is not shown in my machine disclosed in Figure 133, nor in detail in the one disclosed in Figure 112, but the mechanism is so common to the art and has been so thoroughly covered in the above-described patents of mine that I believed it superfluous to repeat them in this connection. Suffice it to state that rocker bar 462c is provided with arms 462 connected by means of a cross bar 452, linked by suitable devices to the camera shutter and the escapement of the carriage of the machine, so that when the rocker bar mechanism is released by the operative movement of bar 450, spring 462b causes the rocker bar to actuate the aforementioned parts of the machine, for successively feeding a fresh surface of the film, or a fresh surface of paper, for the purpose of phototyping or typewriting respectively. With, of course, the restoring to normal rest position of the said rocker bar mechanism, by the returning of the bar 450 into normal rest position, all as set forth hereinabove, completes the round of automatic operation of the typewriting or phototyping machines respectively, to whichsoever type of automatic machine the above-described automatic attachments may be applied.

The most complete typographic machine of all is the one disclosed in Figure 134, comprising mechanism for typesetting, printing and/or typewriting characters, or preferably stamping them on metal tape, for either performing the printing operations, to have lines of printed matter delivered to a phototyping machine for perform-

ing the phototyping operations, or for delivering matrices to a mold for performing casting operations, or for shifting a line of type at a time until a definite number of required lines had been set upon a printing device, for performing printing operations in volume, such as for multigraphing purposes, and so on.

This complete compact machine comprises a keyboard KB of standard typewriter arrangement, a type-basket, letter-bar basket, or punch-and-die basket, Tb for stamping purposes and the mechanism for feeding paper or metal strips or tape to one or the other of two traveling carriages, one on either side of the machine—one, 228, operating in connection with a phototyping machine C, the other, 492, operating in connection with a line casting machine. And a channel 9b² is or may be provided for delivering type to a printing drum, as hereinabove set forth.

Carriage 492 is of sprocket and chain construction, and carriage 228 is likewise of sprocket and chain construction, all structures in this machine being manually controlled and operated from the keyboard KB or levers on the machine. Carriage 492 comprises sprocket wheels 501, 502, mounted respectively upon rotatable bar 410K and 410R, in pairs, one wheel at either end of said bars, all of said wheels in operative connection with chains 492, said chains being arranged to carry one or more molds 493a, 493b and 493c, being shown in the present machine, the arrangement and operation of which is similar to the sprocket and chain carriage of the machine shown in Figure 55, wherein three line-holding carriers are moved by the carriage to respective positions on the machine: one, to a position where it receives a line of type or a printed tape, another where it is backed, a third where it is photocopied.

In the present machine, the mold carriage 40 comprises three molds carried thereby to corresponding positions on the machine: one mold 493a carried to a position where it receives a line of matrices, the second 493b to a position where, having a line of matrices in its matrix channel 45 already inserted, it receives molten metal from melting pot MP, to make the slug casting; the third, 493c to a position where the slug is ejected, preferably by gravity into a receiving compartment 500. With the next travel of the carriage 50, mold 493c is delivered to the position occupied by 493a; the latter, to the position occupied by 493b, the latter, to the position occupied by 493b. Mold 493c, upon arriving at the matrix-receiving position, spring-pressed guide plate 498, is arranged to move it out of its path of travel, until it moves beyond said plate, which then springs back to its normal rest position by the action of its spring, to act as a guide for the ejected line of matrices, which is ejected at this point, by the coacting of a cam edge on a fixed structure 497, with a flange 493f on mold 493, as it is about to assume its position for receiving a new line of matrices, causing the used line to be ejected by means of gravity, to slide along spring-pressed plate 498 and into a channel 499. The mold being divided into two parts, the mold proper for receiving the metal, and the channel for receiving the matrices, being both joined together by spring-pressed pins 493sp, one at either end of the mold, which allows of the separation of the two parts, by the pressure of the cam edge 497 upon the flange, for the ejection of the line of matrices.

- The casting being done at the position where mold 493b is disclosed, the opening to the mold being shown upward and in apposition with metal holding receptacle 21 in connection with the melting pot MP, the other end of the mold, containing the line of matrices, being supported upon plate 497; the said mold 493b being arranged to receive the metal, to be moved across the path of one or more knives for trimming the bottom of the casting, to continue its movement with the travel of the carriage under preferably a water-cooled cover 496, to end up at the ejecting position for the slugs, for emptying its contents into channel 500. The phototyping carriage having already been fully described, I will proceed to explain the manner of operation of the mold carrying carriage and the slug casting mechanism, to complete the description of the entire typographic armamentarium:
- The manner of delivering a line of matrices into the mold channel has been hereinabove fully described, and I need but touch upon the specific features of the present delivery, to make this operative phase of the machine clear to those who will be called upon to study it and dissect it for whatever purpose they may have in view. For this present machine unit, the stamping devices of the machine shown in Figures 113 and 114 are preferred, for stamping justified or unjustified complete lines of matrices or depressed type, to be delivered into the mold channel. The devices for justifying, fully described in the preceding pages, are or may be incorporated in the present machine, it being deemed unnecessary to include them in this figure also, when the matter had been plently illustrated and described already. Upon completion of the stamping of a line, the said line is or may be cut off by means of knife 495, operated by a space bar such as 2s in Figure 55 and shifted into the channel a distance, when the line is locked by the aforementioned means, and either automatic means controlled from a switch, such as hereinabove described does or may perform the series of operations set forth herein, or as disclosed in the present machine, a hand-foot operated lever does or may upon operation either by hand or foot, perform the operations set forth: first, operating the melting pot for performing the casting operations, then moving the carriage for delivery of the corresponding mold to their respective positions as set forth. The said lever 489 being provided with a handle 490, a link 491 pivotally attached to said lever by one end, being connected with a foot lever for operating the said lever 489, when desired; lever 489 being pivotally mounted upon the machine frame at 488, and carrying upon its rear end 487 a one-way trip actuator 481, provided with a guide end 482 in loose operative connection with arm 480 of rocker bar 478; said one-way actuator being pivoted upon the said foot-hand lever at 483 and comprising a spring-pressed arm 484, maintained in normal rest position by spring 486 and stop 485. The rocker mechanism comprising a cross bar 479 connecting arm 480 with another arm 480a on the other end of said bar, to which latter arm is pivoted one end of link L², the other end of which is pivotally attached to lever L in operative connection with the plunger of the melting pot.
- It is obvious that the initial movement of the hand-foot lever 489, causes the one-way actuator 75 to operate the rocker bar mechanism for operat-
- ing the plunger lever of the melting pot for performing the casting operations, and in its further movement, it is arranged for the one-way actuator to release the arm 480 of the rocker mechanism, to allow of its return to normal rest position by the operation of its own spring means as well as the spring means of the aforementioned lever, not shown, after the casting operations have been performed. The movement of the lever continued, rack 468, provided with a teeth set 469 is caused to move for actuating toothed wheel 470, mounted upon rotatable shaft 470R controlling the movement of the carriage 492, for carrying the molds to their respective destinations. This operation of the rack and its operably connected structures is accomplished through the following mechanism: a link 476 connecting the rear end of lever 489 with a lever 474 pivoted at 475, the other end of which lever is pivotally attached to one end of link 473, the other end of which is pivotally attached to rack 468 at 472p, a guiding pin for guiding the movement of the rack at one end in a guide 472, while the other end is maintained by a spring in a meshable position with reference to said toothed wheel 470, provided with a pawl 471, so that the return of the rack will not cause said wheel to move and the various molds will remain in their relative positions for carrying out their various functions. Oblique teeth 30 are provided with that object in view, and spring 468sp allowing the rack teeth to move past said wheel without affecting its stationary position, and to restore the rack into meshable position with reference to said wheel 470 upon return of 35 the rack to normal rest position, upon release of lever 489, when spring 489sp causes it to return to normal position and all the structures connected therewith to return to their respective normal positions; the one-way actuator, upon 40 its return, being itself actuated as it encounters the arm 480 of the rocker bar mechanism which it erstwhile operated for performing the casting operations, the said one-way actuator returning to its normal rest position by its own spring means 45 486 upon passing over said arm to engage therewith by its guide end 482, in position for the next operation of the lever 489.
- Having thus fully described my inventions, what I claim as new and desire to cover by 50 Letters Patent, is:
1. A typesetting machine comprising a series of carriers arranged to severally deliver matrices to a common point mechanism for making new matrices, mechanism in operative connection with said carriers for supplying fresh matrices to said carriers, and means for moving the said carriers severally and successively into operative position for performing the setting operations and additional means for operating the supply mechanism, all of said mechanism being in operative connection with a keyboard and controllable therefrom.
  2. In a typesetting machine a series of type-holding carriers in operative connection with 65 a keyboard and arranged to be severally moved to a common point for performing the typesetting operations, stamping mechanism in operative connection with said carriers and arranged to stamp individual characters, means for feeding said characters to said carriers for replenishing the supply of types in said carriers, the said stamping mechanism being arranged to be automatically operated, power means in operative connection with said stamping mechanism and 70 75

means for moving said carriers being controlled from a keyboard.

3. In a typesetting machine a typesetting unit in combination with a type-making unit, the latter unit being arranged to supply fresh type to the typesetting unit for replacing the ones ejected during the typesetting operations, means in operative connection with a keyboard for operating the typesetting unit for performing the typesetting operations and means independent of the former means for operating the type-making unit.

4. In a typesetting machine a matrix-setting unit in combination with a matrix-making unit, the latter unit being arranged to supply fresh matrices to the matrix-setting unit for replacing the ones ejected during the setting operations, mechanism for operating the matrix-setting unit for performing the setting operations and mechanism independent of the latter for automatically operating the matrix-making unit for the purposes herein set forth.

5. In a typewriting machine printing mechanism arranged to perform printing operations in combination with feed mechanism for feeding the paper a step at a time, said mechanism comprising feed rolls, one of said rolls being mounted upon a rotatable shaft and arranged to be rotated thereby, a toothed wheel mounted upon the said shaft being adapted to rotate said shaft and said feed roll, a lever in loose operative connection with said toothed wheel for operating the said wheel, a carrier upon which the said lever is mounted and arranged to be moved thereby into operative engagement with said toothed wheel for rotating said feed roll, for performing the feeding operations, a universal bar linked to said carrier and means in operative connection with a keyboard for actuating said universal bar.

6. In a typographic machine comprising printing mechanism for performing the printing operations, feed mechanism for performing feeding operations, a knife in operative connection with a keyboard for cutting off the fed material after each printed word or short phrase and to shift said word a distance, mechanical devices arranged to be severally inserted between the said words as constituting a line of printed matter, means being provided for actuating said mechanical devices and a justifying actuator for moving said mechanical devices a distance between the words for performing the justifying operations, as hereinabove fully set forth.

55. 7. A typographic machine comprising printing mechanism for performing printing operations, a carrier having a channel adapted for receiving a line of printed matter, said printed line being arranged to be severed between words or short phrases, a knife in operative connection with a keyboard for performing the cutting operations, a spacing device carrier, a series of spacing devices arranged to be fed, one at a time, to said carrier, means in operative connection with a keyboard for operating said spacing device carrier for delivering a spacing device into said channel after the cut off word, and a justifying actuator for moving the set spacing devices a distance into the channel aforementioned, between the cut words, for justifying the line.

70. 8. A typographic machine comprising mechanism for setting type or matrices and means controlled from a keyboard for justifying a set line of type or matrices, said justifying means comprising a spacer device carrier, a plurality of

springed spacing devices arranged to be fed thereto, one at a time, means in operative connection with a keyboard for actuating said carrier to cause it to deliver a sprung spacing device after a word, and a justifying actuator moving the set sprung spacing devices a distance into the channel between words for justifying the line of type or matrices.

9. A typographic machine comprising stamping mechanism arranged to perform stamping operations, said stamping mechanism comprising a series of moveably mounted punch and die bars arranged radially and adapted for movement to a common point, said punch and die bars severally embracing a punch member moveably attached to a die member and arranged to occupy a normal rest position with reference thereto, and mechanism controlled from a keyboard for operating said moveably connected bars for performing the stamping operations, as herein fully set forth.

10. A typographic machine provided with stamping mechanism for performing the stamping operations, said stamping mechanism comprising a series of moveably mounted punch and die bars arranged to severally move to a common stamping point, each bar embracing a male and a female member moveably connected to each other, means being provided for maintaining said members in a normal rest position with reference to each other, a stamping device arranged to perform stamping operations, means for moving said bars severally to a common stamping point in said stamping device, and mechanism controlled from a keyboard for automatically operating the stamping device for performing the stamping operations.

11. A machine comprising stamping mechanism for performing stamping operations, said stamping mechanism comprising a series of stamping units movably mounted in said machine and severally arranged to perform stamping operations, a stamping mechanism for operating with said stamping units for performing the stamping operations, means for moving said units severally to a common stamping point in said stamping device, a lever in operative connection with said stamping device and arranged to operate said device, a mechanical device in operative connection with a keyboard for moving said lever into a position to allow of its operation for operating the stamping device, the end of said lever movably connected with said mechanical device being arranged to move in a guide slot for guiding its movements back and forth, the said mechanical device being provided with a cam slot for moving the said end of the said lever into and out of operative position in said guide slot and for maintaining said lever in said respective positions, and more particularly in said operative position, a revolute cam being arranged to operate said lever when it is moved by said mechanical device into its operative position with reference to said revolute cam, and means for automatically operating the said revolute cam, to cause the said stamping mechanism to operate with said stamping units severally delivered into operative position with reference to said stamping mechanism for automatically performing the stamping operations.

70. 12. In a typographic machine printing mechanism arranged to perform printing operations, justifying mechanism comprising a plurality of keys, a universal bar in operative connection with said keys, the connecting means embracing

- a plurality of justifying actuators, one to each corresponding key, said actuators being so positioned with reference to the universal bar as to cause said universal bar to move a variable distance with the operation of the several justifying keys, feed mechanism in operative connection with said universal bar being thereby arranged to move a variable distance for feeding a variable sized strip between words to produce the proper spacing to justify the line.
13. In a typographic machine stamping mechanism controlled from a keyboard for performing stamping operations, and means for justifying the lines of stamped characters to produce lines of equal length on a page, said justifying means comprising a universal bar, justifying actuators in loose operative connection therewith and severally so positioned with reference thereto as to cause it to move a variable distance with the corresponding operation of the keys, all as set forth in the preceding claim.
14. A combination of typographic machines comprising a typesetting unit, a printing unit, a casting unit and a photoprinting unit, in operative connection with one another and arranged to cooperate with one another through their operative connection, for successively and consecutively performing their respective functions with reference to the combination of typographic machines and with reference to each other, power-driven means being provided for automatically operating the machine units, for performing their respective functions.
15. A combination of typographic machines embracing several related units in operative mechanical connection with one another, arranged to cooperate with each other for successively and consecutively transmitting through their respective connecting structures progressive operative movement to their related units, for operating the said related units, successively and consecutively.
16. A combination of typographic machines embracing a plurality of related typographic units in operative connection with each other, mechanical means of one of said units being arranged to operatively connect with mechanical means of one or more other units therewith connected, for successively operating the said units for performing their respective operations, mechanical means being provided, controlled from a keyboard, for initiating the respective operations of said typographic units, for automatically performing their respective operative functions.
17. In a combination of typographic machines, embracing a number of related typographic units, mechanism for structurally and operatively linking said units being provided, as controlled from a keyboard, for making said units dependent upon each other for the performance of their respective functions, to the end that the operative mechanism of the linked machines are actuated successively and consecutively upon the release of the controlling means, for the performing of their relative functions.
18. A combination of typographic machines, comprising a casting unit, a photoprinting unit, a line printing unit, a typesetting and a type-writing unit, mechanical means operatively connecting the latter unit with the casting unit for delivering a line of matrices thereto and for subsequently actuating said casting unit for the performance of the casting operations, mechanical means also operatively connecting the said typesetting unit with a line printing machine for delivering a line of set type to said line printing machine and for subsequently actuating the said line printing machine for the performance of the printing operations; mechanical means also operatively connecting said setting and printing units with a photoprinting machine for delivering printed matter to its focal slot for performing the photoprinting operations; all of the aforementioned machines cooperating with one another through their connecting operative mechanisms to perform their respective operations successively and consecutively, individually and collectively, their operations being controlled from a keyboard.
19. In a combination of typographic machines, the compact arrangement of machine units, embracing typesetting, line casting, printing and photoprinting units cooperating with one another structurally and functionally to make a complete printing armamentarium, one unit arranged to set and deliver to a casting mold, the set product; another designed to print lines of printed matter for delivery to the focal slot of a photoprinting machine, another for performing photoprinting operations, another for developing the photographed matter, all mechanically connected with the typesetting unit, provided with a keyboard, from which the typesetting and the respective operations of the other units are controlled by manually operated means.
20. In a combination of typographic machinery, a matrix machine in operative connection with a casting unit, to which it is arranged to feed matrices for performing the casting operations; said matrix machine comprising a series of typeholders for severally carrying the matrices and mechanism in operative connection with said holders for steadily making fresh matrices and refilling said holders with fresh matrices.
21. A typesetting machine in operative connection with a number of typographic machines, and more particularly with a line casting machine, comprising mechanism for setting and delivering a line of matrices to the casting mold for performing the casting operations; the said mechanism comprising a matrix carrier arranged for movement in and out of a common setting point and mechanism for automatically feeding the said carrier with a fresh supply of matrices to replenish the supply used up during the setting operations, the said mechanism comprising stamping means for stamping depressed characters into slugs fed to said stamping means, severally and successively, for performing the stamping operations, to be subsequently fed to said matrix carrier, for replenishing the supply of matrices used up during the setting operations, means being provided for moving the carrier in and out of operative position and additional means for operating the stamping means for performing the stamping operations, for the purposes set forth.
22. A typesetting machine comprising typesetting mechanism and typestamping mechanism in operative connection with each other, the said stamping mechanism being arranged to stamp fresh type and to feed same to the typesetting mechanism for replenishing the supply of type used up during typesetting operations, the said stamping mechanism comprising punch and die means for stamping individual type and ejecting same into feed channels, arranged to feed a type carrier, arranged to be delivered into operative position for performing the typesetting opera-

tions, means being provided for actuating the typesetting mechanism for the purposes set forth and additional and independent means for operating automatically the said stamping mechanism, for the purposes herein set forth.

5 23. A typesetting machine comprising a keyboard, a typesetting unit, a typesetting unit, means operably connecting said typesetting unit with said keyboard, from which the operations 10 of the said typesetting unit are controlled, power means for automatically operating the said stamping unit, as controlled from said keyboard and arranged to perform stamping operations, means operably connecting the stamping with 15 the setting unit to allow of the delivery of fresh type to the setting unit, means being provided for feeding individual type successively and consecutively to a common point.

24. In a typesetting machine the combination 20 of a typesetting mechanical unit with a typesetting mechanical unit, the latter being arranged to keep refilling the typesetting unit, with the typesetting operations, for maintaining a steady supply of fresh types in the typesetting 25 unit, the latter comprising a typeholding carrier in operative connection with a keyboard, means controlled by said keyboard for actuating said carrier and performing the typesetting operations, with additional independent means for actuating the typesetting unit, for feeding newly stamped type to said type-holding carrier.

25. In a typesetting machine a typeholding carrier arranged to be moved in and out of a common setting position, mechanism in operative 30 connection therewith and with a keyboard for actuating said typeholding carrier for the performing of the typesetting operations, punch and die mechanism for stamping fresh type, a magazine arranged to supply fresh blanks for the 35 stamping of new types, automatic power means for operating said punch and die mechanism for performing the stamping operations, means for ejecting the newly stamped type into a feed channel, to be delivered to said typeholding carrier for replenishing the supply of type as it is 40 used up in the course of the typesetting operations.

26. In a typesetting machine a typeholding carrier arranged to hold and set type in a channel, 45 controlled from a keyboard in operative connection therewith, a mechanical device pivotally mounted upon a machine support and arranged to be swung into alignment with the operative end of the operated typeholding carrier, for receiving said operative end therein as a guide and common setting point, a receiving slot in said 50 mechanical device for receiving the type contained in the type holder, arranged to drop by gravity into said slot and upon return of the carrier to normal position to allow of the return of said mechanical device to its rest position overhanging the said channel, for feeding the type it 55 contains into said channel, and means in operative connection with a keyboard for actuating the 60 said mechanical device simultaneously with the operation of the said carrier, for the purposes herein set forth.

27. In a typographic machine a combination 65 of a typeholding type bar arranged to perform typewriting operations and typesetting operations, simultaneously when required, the said bar comprising a typehead carrying printing type, arranged to perform printing operations, and a 70 rectangular chamber for holding type for setting 75

purposes, means being provided to allow of the combined printing and setting operations, and mechanism controlled from a keyboard for actuating said means to allow of the operation of the typewriting mechanism alone.

5

28. In a typewriting machine a type bar having a receptacle in the operative type head for holding a type or a matrix and arranged to perform typewriting operations and successive type or matrix setting operations, means being provided for opening a channel to allow of the combined setting and typewriting operations when required, the said means being arranged to close the said channel for preventing the setting operations and allowing of the typewriting operations solely, mechanism controlled from a keyboard being provided for operating the typeholding type bar and adjusting the said means for closing and opening of said channel, for the purposes as set forth.

20

29. In a typographic machine the combination of a printing unit with a photoprinting unit in operative connection with each other and mechanically dependent upon each other for performing their respective operations, in a manner so as to practically form a composite typographic unit; means being provided, controlled from a keyboard for operating the printing and photoprinting units successively, for the performing of their respective functions, the one, of printing, setting and delivering of the printed matter to the latter unit, to allow of the photoprinting operations to be performed by the other.

25

30. In a typographic machine the combination of a keyboard controlled typewriting-printing-typesetting machine with a photoprinting-engraving machine, arranged to perform their respective functions as set forth herein by the operation of mechanical devices connecting the two machines abovementioned and controlled partly 40 from a keyboard and partly from a lever for actuating the said mechanical devices, for operating the said machines.

35

31. A typographic machine comprising a keyboard controlled typewriting-printing-setting unit and a photoprinting unit in intimate operative connection with one another by mechanical devices linking the two machines structurally and functionally, said mechanical devices being arranged to operate mechanism of the former and 45 the latter, simultaneously and consecutively, for operating the said machines, for performing their 50 respective operations.

40

32. A typographic machine comprising a typewriting-printing-setting unit controlled from and 55 operated by means of a keyboard, and a photoprinting unit to which printed matter is arranged to be delivered for the performing of photoprinting operations, mechanism being provided in operative connection with the two units for moving the printed matter to the focal slot of the photoprinting machine for the performing of the photoprinting operations, and means in operative connection with both units for operating said 60 mechanism.

50

33. The combination of a typewriting machine with a photoprinting machine into a single working unit, arranged to be controlled from a keyboard and a lever, the said lever being in operative connection with structures of the typewriting machine and with structures of the photoprinting machine, and being arranged to 65 actuate the said structures, for operating the said combined machines, to cause them to perform 70 their respective operations, a traveling carriage 75

65

- for carrying written-printed matter from the typewriting machine to the focal slot of the photoprinting machine, for performing the photoprinting operations, the said traveling carriage movements being controlled by the operation of said lever, which also controls the operation of the photoprinting machine devices, for performing the operation of photoprinting.
34. A typewriting machine comprising a type bar in operative connection with a keyboard and arranged to be operated therefrom, a stationary platen against which the printing end of the type bar is arranged to impinge and with which it is arranged to cooperate for performing the printing operations, feed mechanism for feeding suitable material upon which the printing operations are arranged to be performed, the said feed mechanism comprising a pair of feed rolls, a spool of tape source of supply to said rolls, and means in operative connection with a keyboard for feeding the said tape of writing material a step at a time, for receiving the imprint of the operated type bar, for the performing of the printing operations.
35. In a typewriting machine a type bar in operative connection with a keyboard arranged to perform printing operations, a stationary platen with which the said type bar is arranged to coact for performing the printing operations, mechanism for feeding a strip of suitable material, a step at a time, for receiving the type imprint, said mechanism comprising a pair of feed rolls, a universal bar in operative connection therewith being arranged to operate the type bar for the performing of printing operations, simultaneously with the operation of the feed mechanism for delivering a fresh piece of tape for receiving the imprint, means connected with said feed rolls being actuatable by the said universal bar for feeding the tape a step at a time, for performing the printing operations.
36. A typewriting machine arranged to perform printing operations, suitable feed mechanism for feeding paper a step at a time for receiving the imprint, means to which the printed matter is arranged to be delivered, for carrying the said printed matter to a definite destination lying in the path of travel of said provided means, other mechanical elements in loose operative connection with said means for performing definite operations indigenous to said destination and means for operating said mechanical elements.
37. A typewriting machine provided with printing mechanism for performing the printing operations, a traveling carriage, line holding carriers mounted thereon and arranged to be carried thereby to definite destinations, the said carriers being adapted to receive printed matter, for delivering the said matter to corresponding predetermined positions, for performing operations indigenous to said positions, and mechanism for operating the said carriage, for the purposes herein set forth.
38. A typewriting machine comprising printing mechanism arranged to perform printing operations, a traveling carriage embracing sprocket and chain means of travel, channeled carriers mounted thereupon and arranged to be moved thereby to predetermined positions along its path of travel, printed matter arranged to be fed to said channeled carriers, for delivery to corresponding positions, for performing operations indigenous to such positions, mechanical means cooperating with said channeled carriers for the performing of the said operations, and means for actuating the said mechanical means.
39. In a typewriting machine arranged to perform printing operations, a traveling element comprising chain and sprocket means, channeled carriers mounted thereon and arranged to be moved thereby into corresponding operative positions, printed matter arranged to be fed to said carriers, a photoprinting machine arranged to photoprint the printed matter delivered into the focal slot by said carriers, and mechanism controlled by a lever for performing the photoprinting operations.
40. In a typographic machine comprising a typeprinting unit and a photoprinting unit, the former comprising printing mechanism arranged to perform printing operations, the latter comprising a camera for performing the photoprinting operations, a traveling element comprising chain and sprocket means, channeled carriers mounted thereon and arranged to be carried thereby to predetermined positions with reference to the typographic machine: one to the printing position for receiving a line of printed matter, another to a pasting position for receiving a back, the third to the photoprinting machine for performing the photoprinting operations, the said carrier comprising a channeled groove for receiving the said printed matter and a sprung device for maintaining the said printed matter in a fixed position in the channel, mechanism for moving the said carriage, for delivering the said carriers to corresponding positions with reference to said machines, and a manually operated lever for operating said mechanism for delivering one of said carriers to the printing position to coact with means allowing of the ejection of the line of photoprinted matter, another to the photoprinting position for performing the photoprinting operations, and a third to the pasting position, as herein fully set forth.
41. In a typographic machine, printing mechanism for performing printing operations in combination with a photoprinting machine arranged to perform photoprinting operations, mechanism for justifying lines of printed matter, a channeled carrier for receiving a line of printed matter, in words and short phrases, cut apart, to allow of the justifying of the line, and a justifying actuator, for performing of the justifying operations.
42. In a typographic machine, printing mechanism arranged to perform printing operations, a channeled carrier adapted for receiving a line of printed matter, a knife for cutting the printed tape at the end of each word or short phrase, spacing devices arranged to be inserted into the channel of said carrier between the printed words delivered thereto, one spacing device after each word or short phrase, said spacing devices being controlled from a keyboard in regard to their individual delivery between words, a justifying actuator for performing the justifying operations, a manually operated lever in operative connection with said justifying actuator, being arranged to operate said actuator for performing the justifying operations.
43. A typographic machine comprising printing mechanism for performing printing operations, a channeled carrier arranged to receive a line of printed matter, a knife for cutting the said line into words or phrases, directly after the word is printed, spacing devices arranged to be inserted between words, an actuator for individual spacing device operation as controlled from a key-

board, a justifying actuator for justifying the line by shifting the said spacing devices a distance into the channel of the carrier between words, the said spacing devices each comprising a sprung member, which when moved between words into said channel tends to evenly spread apart the words, to properly justify the line, and a lever adapted for manual operation, for operating the said justifying actuator.

44. A typographic machine comprising a typesetting unit, a type casting unit and a photoprinting unit arranged in compact form in one composite machine, the photoprinting attachment comprising elements and operations as hereinabove set forth, the casting unit embracing a traveling carriage as in the former, casting molds mounted upon said traveling carriage and arranged to be carried thereby to predetermined positions with reference to the machine; one into the typesetting position where it is arranged to receive a line of matrices, another into a position for receiving the metal for performing the casting operations, a third into the ejecting position for ejecting the cast slug, the said one in the typesetting position being arranged to discharge its used matrix line as it arrives at its setting destination, means being provided for that purpose, to allow of the setting of another line of matrices, to repeat the rounds of interchangeable operations, a hand-foot lever being provided, in operative connection with the said casting mechanism, for operating same, for performing the casting operations.

45. In a typographic machine the combination of a typesetting machine with a typecasting machine, the latter being provided with a traveling carriage, a mold mounted thereon and arranged to be carried thereby to predetermined positions with reference to the path of travel of the said carriage, means being provided at each of the said predetermined positions to which the said mold is delivered, arranged to coat with said mold, for performing corresponding operations indigenous to the said predetermined position,—being arranged to feed matrices to the mold in one position; to perform typecasting operations in another position; ejecting operations in a third

position, for cast slug ejections and a matrix ejecting operation for ejecting used matrices, in the matrix feeding position, means being provided coacting with means on the mold for causing said mold to eject the used line of matrices, for allowing of the insertion into the matrix mold channel of a fresh line of matrices, and means controllable from a mechanical device movably mounted upon the machine operably connecting with said carriage and the casting means, for performing the casting operations and for moving the carriage to deliver said mold into its predetermined positions.

46. A machine provided with stamping mechanism for performing stamping operations controlled from a keyboard, and comprising a series of stamping units arranged to severally move to a common stamping point, each stamping unit comprising a male and a female member movably attached to each other, means being provided for maintaining said members in a normal rest position with reference to each other, a stamping device arranged to perform stamping operations, means for moving said stamping units severally to a common stamping point in said stamping device and power-driven means controlled from a keyboard for operating said stamping device for performing the stamping operations.

47. In a typographic machine a series of character stamping units moveably mounted therein and arranged to severally perform stamping operations, a stamping device for cooperating with said units for performing stamping operations, means for moving the said units severally to a common stamping point in said stamping device, a lever in loose operative connection with said stamping device, a mechanical device in operative connection with a keyboard for moving the said lever into a position to allow of its operation for actuating the stamping device and a revolute cam for actuating the said lever when moved into said position, for operating the stamping device to cause it to perform the stamping operations, and power means controlled from a keyboard for automatically operating said cam.

ALEXANDER BLOCK.
